FIG. 6

This circuit diagram illustrates a complex electronic network, likely a telephone switch or similar system. The diagram is organized into several functional blocks:

- Left Side:** Features a large rectangular block containing resistors 601, 610, and 633. This block is connected to a terminal labeled 631 (610) and a switch labeled 632.
- Middle Section:** Contains a large rectangular block labeled "MARGINAL" at the top. It includes resistors 604, 605, 606, 612, 620, 621, 623, 624, 625, 626, 627, 628, 629, 630, and 631. A "TONE SOURCE" is connected to terminal 630.
- Right Side:** Shows a terminal labeled 600 at the top. Below it are resistors 602, 603, 605, 607, 608, 617, 620, 621, 623, 624, 625, 626, 627, 628, 629, 630, and 631. A small switch is also present on the right side.

The connections are dense, with many lines branching off from a central vertical bus. Various logic gates and resistors are interconnected to form the logic and signal paths of the circuit.

UNITED STATES PATENT OFFICE

WILLIAM HATTON, CHARLES DE VRIENDT, AND ERNEST JEAN ROUSSEAU, OF PARIS, FRANCE, ASSIGNORS TO WESTERN ELECTRIC COMPANY, INCORPORATED, OF NEW YORK, N. Y., A CORPORATION OF NEW YORK

DIAL SWITCHING RURAL TELEPHONE EXCHANGE SYSTEM

Application filed March 8, 1930, Serial No. 434,214, and in Great Britain March 18, 1929.

This invention relates to automatic telephone systems and more particularly to telephone exchange systems which may comprise district offices grouped around a center office, the center office in turn being connected to a main office. The object of the invention is to enable the establishment of connections in an exchange system comprising a number of small district or community offices employing uniform directory numbering for all telephone lines by discriminating as to the designation of all calls whereby the smallest amount of equipment commensurate with efficient service is retained in use on any call. The embodiment of the invention disclosed herein comprises a rural exchange system composed of one or more offices. Connected to the main office are one or more center offices in which register translators are provided. Connected to the center offices directly is a number of district offices. Some of these district offices may be of the tandem type to which one or more smaller district offices are connected. Tie lines may be provided, if desired between any of these offices, although such facilities will not be described herein. For all calls within the exchange system a trunk or trunks to the center office concerned is or are automatically taken for use and the wanted subscriber's number is dialed into a register translator at the center office. The uniform numbering scheme obtains throughout the exchange system and the total number group allotted to the system may be divided among the offices on a non-decimal basis. For example, a group of 20,000 subscribers' lines is allotted to the system and the individual offices are allotted groups of 100 lines or multiples of 100 or 1000. It is also desirable to provide full automatic zone metering facilities throughout the system and in order to make the apparatus required therefor as simple as possible, it is necessary to provide such facilities at the originating offices in every case. If such facilities were provided at an office other than the originating office, it would be necessary to provide discriminating means whereby the identity of the calling office would be recognized. In order to provide zone metering facilities at each office, it is necessary to include some digit discriminating means thereat. For this purpose register translator circuits which will hereinafter be called discriminating registering devices are associated with the trunks outgoing from all district offices and the register translators at the center office will also include means whereby zone metering operations may be performed. Claims specifically directed to the zone metering features of the exchange system are being presented in our copending application Serial No. 434,216, filed concurrently herewith.

At the center office the register sender is provided with a translator switch having five levels of 50 terminals each. Four of the levels of terminals are arranged in pairs and since the first digit of a called line number within the exchange system has only two variations, one pair of levels of the translator is chosen in accordance with the setting of the first digit register of the sender. One level of the pair is chosen by the setting of the second digit register in accordance with the odd or even value of the second digit. The fifth level of the translator is used for setting the wipers of the translator in accordance with the setting of the third digit register. The translator may therefore be set to a particular terminal out of 200 terminals in four of its bank levels. These terminals are commoned in accordance with the size of the various offices of the exchange system and the commoned terminals are jumpered to particular terminals in a marking level of a 50 point translated digit controlling switch. The latter switch comprises levels over which the translated digits are determined and a level or levels over which switching devices may be operated for varying the number of digits to be sent out and the control means therefor.

Referring to the drawings, Fig. 1 shows at 95 the left a subscriber's line, one of the link circuits of the community office terminating at one end in a line finder and at the other end in a plurality of parallelly connected group selectors, tens and units marking

switches for controlling the settings of the group selectors and at the right one outgoing trunk circuit and a subscriber's line terminating in the bank of one of the group selectors.

5 Fig. 2 shows the apparatus associated with the outgoing end of the trunk circuit and in the lower right portion of the figure a message register impulsing switch for controlling the calling line message register of Fig. 1 in accordance with the zone of the exchange into which a connection is extended.

10 Fig. 3 shows a discriminating registering device for registering and translating the first three digits dialed by a calling subscriber together with a trunk finder switch, shown in the upper portion of the figure, whereby the registering device may be associated with any one of a group of trunk circuits.

15 Fig. 4 shows at the left the incoming end of the two-way trunk circuit shown in Fig. 2, one of the link circuits of the tandem office terminating at one end in a line finder having access to both incoming trunk circuits and subscribers' lines and at the other end in a group finder having access to outgoing trunks such as shown in Fig. 6 and to local third group finders (not shown).

20 Fig. 5 shows a tandem register sender for controlling the establishment of connections to subscribers' lines terminating in the tandem office and a link finder individual thereto for associating it with a tandem link circuit.

25 Fig. 6 shows an outgoing trunk circuit and in the lower right portion of the figure a message register impulsing switch for controlling the message registers of calling lines which are local to the tandem office.

30 Fig. 7 shows a discriminating registering device for registering and translating the first three digits dialed by a calling subscriber in either the district office of Fig. 1 or the tandem office of Fig. 4 together with a trunk finder switch individual thereto, whereby the registering device may be associated with any one of the outgoing trunk circuits such as the trunk circuit shown in Fig. 6.

35 Fig. 8 shows in the left portion thereof, the incoming end of a trunk circuit incoming from the tandem office of Fig. 4, and the line finder end of a link circuit of the center office.

40 Figs. 9 and 10 taken together show a translator type register sender of the center office. Fig. 9 shows in the upper portion thereof a link finder by means of which the sender may be associated with a link circuit such as shown in Fig. 8 or with a link circuit such as shown in Fig. 15, in the left portion thereof a register steering switch and in the right portion an impulse counting switch. Fig. 10 shows the digit registers of the sender, a translator switch and a translated digit switch.

45 Fig. 11 shows a group selector of the center office in which the link circuit of Fig. 8 terminates.

50 Figs. 12 and 13 taken together show a final selector of the center office. Fig. 12 shows the apparatus of the final selector and Fig. 13 showing a control switch common to a group of final selectors for controlling the setting thereof.

55 Fig. 14 shows a group selector or direction switch of the center office.

60 Fig. 15 shows a subscriber's line local to the center office and a link circuit having a line finder and group selector by means of which the subscriber may establish local or outgoing connections.

65 Fig. 16 shows in diagrammatic form the circuits of the exchange system illustrated in the before-mentioned figures.

70 Fig. 17 shows an alternative form of impulsing circuit whereby group selectors may be controlled by register senders.

75 Fig. 18 shows schematically the association of the translator, translated digit switch, digit registers, impulse counting switch and digit skipping and meter controlling relays of the sender of Figs. 9 and 10.

80 Fig. 19 is a diagram showing how Figs. 1 to 15 inclusive, should be arranged to completely disclose the invention.

85 Referring more particularly to Fig. 16 a part of the exchange system has been schematically illustrated as including a main office M, a center office C, a district office D1 connected directly to the center office C, a tandem district office TD connected to the center office C and a district office D2 subsidiary to the tandem district office TD. If a call is initiated by a subscriber S at the district office D1, for example, a connection is at once established over an idle link circuit DLL over the outgoing end OJC of an idle two-way trunk circuit and over the incoming end BWJ2 of such trunk circuit at the center office C. An idle link circuit CLL at the center office is thereupon started to make connection with the incoming end of the trunk circuit over the line finder JF in which one end of the link circuit CLL terminates. This link circuit terminates at its other end in a first group selector GF1.

90 A registering device MCC individual to the district office D1 and common to the trunk circuits outgoing therefrom to the center office is automatically associated with the trunk circuit OJC taken for use and a register sender R4 at the center office C is automatically connected to the line finder link circuit CLL upon the seizure of that link. The calling subscriber receives dial tone when both the registering device MCC and the register sender have become associated and then proceeds to dial the wanted subscriber's number. The discriminating digits of the telephone direction numbers which correspond to office code 130

digits, in the particular embodiment to be described the first three digits, will then be registered in the registering device MCC at the district office D1 and in the register sender 5 R4 at the center office. The registering device MCC in addition to controlling zone metering also discriminates between local and outgoing calls and if the call is found to be local, the trunk to the center office C, the registering 10 device MCC and the register sender R4 are all released, and the remaining two digits dialed by the calling subscriber S are then instrumental in setting the group selector SMS1 or SMS2 in which the district link 15 circuit DLL terminates upon the terminal of the wanted local subscriber's line, such as S1 or S2.

If the call is not to be completed locally, however, the last two digits dialed by the 20 calling subscriber S are registered on registers of the sender R4 of the center office after which impulses are transmitted from such sender to complete the connection to a subscriber's line terminating at the center office, 25 or at or through the main office M. If the wanted subscriber's line terminates in another center office similar to the office C or in a district office auxiliary to such other center office, the call will be routed over the 30 first group selector GF1, a trunk extending to the main office M and the direction switch DS of the main office to such other center office. All calls initiated within the exchange 35 system and passing from the center office C to main office M or outgoing from the exchange system pass over the direction switch DS of the main office. If the call is within the exchange system, the call is passed through the direction switch DS to a second group 40 selector such as GF2 in the wanted center office from which the connection is further extended by way of a third selector, such as GF3 and a final selector FF in such center office or over a two-way trunk to the district 45 office which is auxiliary to such center office. For calls incoming to a district office no registering device, such as MCC, is connected up.

In a tandem group of offices, that is to say, a tandem district office together with the 50 district offices which are satellite or auxiliary thereto, all calls other than calls local to the satellite districts pass through the tandem district office. Since translation may be required within the tandem group, it is necessary to provide a register translator for calls 55 within the group in or passing through a district office. Thus, for a call originating in office D2, a subscriber S3 through a link circuit, such as DLL automatically selects a 60 trunk OJC, BWJ1 extending to the tandem district office TD. The link circuit TLL of the tandem office, in turn, automatically selects an idle trunk OJC, BWJ2 extending to the center office C. Registering devices MCC 65 both in the district office D2 and in the tandem

office TD and the register sender R4 in the center office are then associated with the connection. In addition a tandem register sender R5 common to the link circuits of the tandem office is associated with the tandem 70 office link circuit TLL. The calling subscriber upon dialing the discriminating digits causes their registration in the registering devices of both the district and tandem offices and in the register sender R4 of the center 75 office, but the register sender R5 of the tandem office is held idle at the time. The registering device MCC of the tandem office TD discriminates as to whether the call is local 80 within the tandem group. If this is the case all seized apparatus beyond the tandem is released and the remaining digits are then registered in the tandem register sender R5 which controls the setting up of the connection to the wanted subscriber. If, however, 85 the call was local to the district office D2 the registering device MCC of that office would have initiated the release of all seized apparatus beyond the district office D2 and the last two digits dialed by the calling subscriber S3 would then cause the group selector of the district office to complete the call locally. If the call is outgoing from a tandem group, the register sender R5 of the tandem office is released unused due to the discriminating registration set up in the registering device MCC and the tandem office TD. 90

While no district offices have been disclosed as auxiliary to the main office, such offices might be provided in which case the main 100 office would also be equipped with a register translator sender similar to the register sender R4.

Forward impulsing is used throughout the exchange system and the switches are all of the single motion type, but may be either power driven or of the step-by-step type. Control circuits are provided for the selector switches which are of the finder type. The control circuits may be common to a number 105 of selector switches of the same selecting stage and may combine the functions of a trunk finder and a marking switch.

In the system as illustrated loop dialing is employed, the loop being formed in response to a signal sent back from the selecting stage to which the succeeding digit impulses are to be sent. This signal is sent back over one side of the line with a ground return. If it is desired to eliminate the ground return 115 circuit which has some disadvantages due to difference of ground potential between the several offices of the system, an alternative arrangement of dialing and supervisory circuits may be employed. In this alternative 120 arrangement shown in Fig. 17 forward loop dialing is also used, the line being permanently looped at the selecting stages by loops comprising high resistance. The arrangement at the registering control end is similar 125 130

to that disclosed throughout the circuit drawings, that is, battery is connected to one side of the line by way of the impulse sender and ground to the other side by way of a control relay when the register sender is ready to send out a series of digit impulses. The permanent loop at each selecting stage comprises a high and a low resistance relay.

When the register sender is ready to transmit impulses and battery and ground are connected to the two sides of the outgoing trunk line, the low resistance relay of the loop at the selector is operated to prepare the selector for receiving impulses. When the selector is thus prepared, the high resistance relay becomes short circuited, thus permitting the control relay in the register sender to operate to initiate impulsing. When the control relay operates it becomes short circuited to form a low resistance impulsing loop at the sender. The low resistance relay of the loop at the selector then responding to the impulses. At the end of the impulsing the short circuit of the high resistance loop relay is opened and the register sender prepares for controlling the impulsing to the next succeeding switching stage.

All of the switches disclosed are of the single motion step-by-step type. The line finders 100, 400, 800 and 1500 are of the type having no normal positions and each is equipped with two sets of wipers placed on the switch shaft 180° apart. The selectors 110, 120, 130, 1100, 1200, 1400 and 1510 are of the same general type as the line finders, that is, they are of a hunting type. The group selector 110 has access to a group of five outgoing trunks and to 90 subscribers' lines and the group selectors 120 and 130, the wipers of selector 130 not being illustrated, each has access to 100 subscribers' lines, the group selectors 1100 and 1510 having access to trunks extending to the center office or to trunks terminating locally in group selectors.

The trunk and link finders 300, 500, 700 and 900 are also of the line finder type having no normal position. The marking switches 140, 150, 1300, 1310 and 1410, the message register impulsing switches 200, 420, 600 and 1520, the sender registers 310, 320, 510, 520, 530, 710, 720, 1010, 1020, 1030, 1040, and 1050, the register steering switch 910, and the impulse counting switches 540 and 920 are all minor type switches which are restored to normal when they are no longer required for service. The translator switches 330, 730 and 1000 are of a type having provision for wiper selection each having access to 50 sets of bank terminals and provided for restoration after having completed translating functions. The translated digit switch 1060 and the marking switch 1110 are also 50 point switches.

Initiation of a call from a line local to district office

For a better understanding of the invention reference may be had to the following description in which the progress of a call from the calling line 101 over the circuits of Figs. 1 to 13 inclusive, will first be described in detail. When the calling subscriber removes his receiver from the switchhook a circuit is established from battery, through the winding of line relay 102, the upper back contact of cut-off relay 103, over the loop of the calling line to ground at the lower contact of relay 103. Relay 102 upon operating establishes an obvious circuit for the common group relay 104 which in turn establishes a circuit for the common line finder start relay 105. Relay 105 at its front contacts closes start circuits for the stepping magnets of all idle line finders having access to the group of lines in which the calling line is located. It will be assumed that the line finder 100 is that one of these line finders which is to be used in establishing the connection. The circuit for starting this line finder may be traced from battery, through the magnet winding and interrupter contacts of stepping magnet 106, contacts of relay 105, contacts of test jack 107, back contact of relay 108 to ground at the upper normal contacts of relay 109.

In response to the operation of magnet 106 the wipers of the line finder are advanced until the test wiper 111 engages the test terminal of the calling line. Then a circuit is established from ground, through the lower winding of relay 108, the normal contact of thermostatic relay 112, contacts of jack 107, wiper 111 to battery at the front contact of relay 102. Relay 108 upon energizing closes an obvious circuit for relay 113 and opens at its back contact the circuit of stepping magnet 106. With relay 113 operated ground is connected over the lower contact of relay 113 and the upper winding of relay 108 to test wiper 111 to prevent the seizure of the calling line by other line finders and a circuit is closed for the stepping magnet 114 of the group selector 110 to advance this group selector to hunt for an idle outgoing trunk. This circuit extends from battery, through the winding and interrupter contacts of magnet 114, lower back contacts of relays 115 and 116, lower back contact of relay 109, upper contact of relay 113 to ground at the back contact of test relay 117. When an idle trunk is found, relay 117 operates in a circuit extending from ground at the upper normal contact of relay 118, wiper 119 of marking switch 140 and its normal terminal, strapped terminals with which wiper 121 of the group selector engages, winding of relay 117, inner upper front contact of relay 113, wiper 122, conductor 201 to battery through the winding of relay 202. Relay 202 also operates

70

75

85

90

95

100

105

110

115

120

125

130

in this circuit and performs a function which will be described later.

Relays 117 upon operating, opens the circuit of magnet 114 to arrest the operation of the group selector 110 and establishes over its front contact and a contact of relay 113 a circuit for relay 123. At its inner lower front contact relay 123 applies direct ground through the winding of relay 117 over wiper 122 to conductor 201 to mark the selected trunk busy and closes an obvious circuit for relay 124. Relay 124 upon operating establishes a circuit from ground through the winding of relay 109, over wiper 125 of line finder 100 to battery through the calling line cut-off relay 103. Relay 103 disconnects the line relay 102 which in turn releases relay 108 and if there are at the time no other lines calling in the group, releases common 20 relays 104 and 105 thereby arresting the operation of any other idle line finders that may have been started. After the release of relay 108, relay 113 is locked over its inner lower front contact the back contact of 25 relay 126 to ground at the upper front contact of relay 109.

Relay 202 of the link circuit which operated in series with test relay 117 upon operating establishes an obvious circuit for relay 203. With relay 109 operated a circuit is established from ground, through the upper winding of relay 204, wiper 127 of selector 110, upper alternate contacts of relay 123, lower front contact of relay 109, wiper 128, 35 over the calling line, back over wiper 129, the inner upper contact of relay 109, the inner upper front contact of relay 123, wiper 131 to battery through the lower winding of relay 204. Relay 204 operates in this circuit and closes an obvious circuit for slow to 40 release relay 205 which operates in turn and causes the operation of relay 206. An impulse repeating circuit is now extended over the outgoing conductors 207 and 208 of the 45 trunk circuit for repeating impulses to the office to which the district office is subsidiary, this circuit extending from battery through the winding of relay 401, the lower back contact of relay 402, over conductor 208, back 50 contact of relay 210, the lower back contact of relay 209, upper front contact of relay 204, conductor 207 to ground at the upper back contact of relay 402. Relay 401 operates in this circuit and at its upper front contact 55 closes an obvious circuit for common start relay 403 and at its lower front contact connects battery potential to the test terminal 404 to mark the trunk 207, 208 as calling. Relay 403 upon operating closes start circuits 60 for all idle line finders such as 400 which have access to the group of trunk circuits in which the calling trunk is located.

It will be assumed that the line finder 400 is to be used to extend the connection and that 65 the start circuit for magnet 405 extends from

battery, winding and interrupter contacts of magnet 405, contacts of its jack 406, contacts of relay 403, back contact of relay 407 to ground at the back contact of test relay 408.

When the wipers of the line finder engage the 70 terminals of the calling trunk circuit, test relay 408 operates in a circuit extending from battery on terminal 404, wiper 409, contacts of jack 406, normal contact of thermostatic relay 411, to ground through the upper winding of relay 408. Relay 408 operates opening the circuit of magnet 405 to arrest further motion of the line finder 400 and closes a circuit for operating relay 412, extending from ground at the front contact of relay 408, upper winding of 75 relay 412, to battery at the back contact of relay 413. At its inner upper front contact relay 412 connects ground through the lower low resistance winding of relay 408, to the test wiper 409 to mark the terminals of the 80 calling trunk against seizure by another line finder and at its intermediate lower front contact establishes a circuit for operating relay 414, extending from battery through the winding of relay 414, the contact of relay 412, 85 to ground at the front contact of relay 408. At its contact relay 414 establishes a circuit extending from ground through the winding of relay 407, wiper 415 to battery through the winding of cut-off relay 402. Relay 402 disconnects the line relay 401 from the trunk circuit which upon releasing releases the common start relay 403 to stop all other started 90 finders if there are at the time no other trunks of the group calling. Relay 402 also closes an operating circuit for slow-to-release relay 416 extending from ground through the winding of relay 416, lower back contact of relay 417, front contact of relay 402 to battery. Relay 416 opens the trunk conductor 208 at 95 its back contact but this opening is at the time ineffective since a shunt at the contacts 100 of relay 416 exists over the upper normal contacts of relay 417.

Relay 407 upon operating extends the trunk conductor 207 over line finder wiper 418, the upper front contact of relay 407, the upper back contact of relay 421 to ground through the lower winding of relay 422 and at its intermediate upper front contact extends conductor 208 over wiper 419, the lower back contact of relay 421 to battery through the upper winding of relay 422. At its lower front contact relay 412 connects marking potential to test terminals 501 of all link finders similar to finder 500 of Fig. 5 and in parallel to ground through start relay 502. Relay 502 operates, closing an obvious circuit for relay 503 which in turn establishes operating circuits for the stepping magnets of all 110 idle link finders individual to idle tandem senders. One of these senders is shown in Fig. 5 and it will be assumed that this sender is idle and becomes connected with the link of Fig. 4. The operating circuit of finder 115 120 125 130

500 may be traced from battery through the winding and interrupter contacts of magnet 504, contacts of relay 503, upper back contact of relay 507 to ground at the back contact of relay 505.

When the calling link circuit is found, test wiper 506 of finder 500 engages terminal 501, and the circuit previously traced to terminal 501 is extended over wiper 506, the 10 upper winding of test relay 505, the lower back contact of relay 508 to ground at the normal contact of thermostatic relay 509. Relay 505 thereupon operates, opening at its back contact the circuit of magnet 504 and 15 closing an obvious circuit for relay 512 which in turn closes an obvious circuit for relay 507. Relay 507 at its inner upper front contact now connects ground through the lower low resistance winding of relay 505 to test terminal 501 and at its upper back contact opens 20 another point in the circuit of magnet 504. At its inner upper front contact relay 507 connects ground to conductor 553 for supplying locking ground for relays of the sender and at its lower front contacts prepares 25 circuits from wipers of finder 500. At its lower front contact relay 407 also establishes a circuit extending through the lower winding of relay 413, wiper 511 of link finder 500, 30 both windings of relay 513 to ground on conductor 553. Relay 513 operates but performs no useful function at this time. Relay 413 does not operate due to the resistance of the windings of relay 513.

35 When relay 407 operated a circuit was established for starting the group selector 410 hunting for an outgoing trunk circuit such as is shown in Fig. 6, which circuit may be traced from battery through the winding 40 and interrupter contacts of magnet 423, intermediate upper back contact of relay 424, back contact of relay 425 to ground at the inner upper front contact of relay 407. When an idle outgoing trunk is found, for 45 example, the trunk shown in Fig. 6, relay 425 operates in a circuit extending from ground on the inner upper front contact of relay 412, lower winding of relay 425, upper back contact of relay 426, test wiper 427, conductor 50 601, back contact of thermostatic relay 617 to battery at the upper back contact of relay 615 and to battery over the back contact of relay 602 through the winding of relay 605. Relays 425 and 605 operate, relay 425 upon 55 operating locking from battery on test wiper 427 over its upper winding, through the winding of relay 428, the front contact of relay 425 to ground at the inner upper front contact of relay 407 and opening at its back 60 contact the circuit of magnet 423 to arrest the further hunting movement of the group selector. At its contact relay 428 closes an obvious circuit for relay 429 which operates and locks over its inner lower front contact to 65 ground placed on conductor 430 over the

front contact of relay 414. Relay 605 upon operating closes an obvious circuit for relay 606.

Relay 602 now operates in a circuit extending from ground at the lower back contact of relay 615, upper front contact of relay 606, lower winding of relay 602, conductor 616, wiper 435, inner upper normal contacts of relay 426, upper front contact of relay 429 to battery through the winding of relay 421. 70 Relays 602 and 421 operate, relay 602 connecting battery through its upper winding and front contact in parallel with battery through resistance over the upper back contact of relay 615 to conductor 601 75 to mark the trunk busy to other tandem link group selectors and relay 421 disconnecting the windings of relay 422 from the incoming dialing loop and extending this loop over its upper and lower front contacts directly to the windings of relay 604. At its inner lower front contact relay 421 establishes a new holding circuit for holding relay 414 operated after the release of relay 422. Relay 604 now operates establishing a new 80 operating circuit for relay 605 which in turn holds relay 606 operated.

Returning to the trunk circuit of Fig. 2, relay 206 upon operating at its inner upper contact connects busy potential from the upper back contact of relay 215 over the normal contacts of thermostatic relay 217, resistance 218, contacts of relay 206 to conductor 201 in parallel with relay 202 for holding relay 117 of the district link circuit operated. At 95 its innermost lower front contact relay 206 connects marking potential over the lower back contact of relay 211, the inner lower front contact of relay 206 to test terminals 301 of all trunk finders similar to trunk finder 300 of Fig. 3 and in parallel to ground through start relay 302. Relay 302 operates closing an obvious circuit for relay 303 which in turn establishes operating circuits for the stepping magnets of all idle trunk finders individual to idle registering devices. One of these registering devices is shown in Fig. 3 and it will be assumed that this registering device is idle and becomes connected with the trunk of Fig. 2. The operating circuit of 100 trunk finder 300 of this registering device may be traced from battery, through the winding and interrupter contacts of stepping magnet 304, a contact of relay 303 to ground at the back contact of relay 305. 105 When the calling trunk is found and test wiper 306 of trunk finder 300 engages terminal 301, the circuit previously traced to terminal 301 is extended over wiper 306, the upper winding of relay 305 to ground at the 110 normally closed contact of the off-normal springs 354 of translator switch 330. Relay 305 thereupon operates opening the circuit of magnet 304 and closes an obvious circuit for relay 307 which at its lower front 115

contact connects the low resistance winding of relay 305 into circuit with wiper 306 to busy the trunk circuit to other trunk finder switches.

- 6 Relay 307 also closes a circuit in parallel through the windings of relays 210 and 211 over wiper 308, the innermost upper front contact of relay 307, resistance 355 normal terminal and wiper 309 of register 310, normal terminal and wiper 311 of register 320 to ground at the back contact of relay 312. Relay 210 operates to close the outgoing trunk circuit so that the subscriber may receive a dial tone incoming over the trunk circuit.
- 15 Relay 211 being marginal does not, however, operate at this time because of the resistance 355 in its operating circuit. The continuity of the loop circuit over the outgoing trunk circuit is not, however, broken by the operation of relay 210 since it is maintained through the winding of supervisory relay 212.

Following seizure of the trunk circuit of Fig. 6, it functions in identically the same manner as described in connection with Fig. 2 to cause the association therewith of the discriminating registering device of Fig. 7, and to establish an out dialing loop extending to the center office which may be traced from battery, winding of relay 801, lower back contact of relay 802, trunk conductor 608, winding of relay 612, lower back contact of relay 609, upper front contact of relay 604, trunk conductor 607 to ground at the upper back contact of relay 802. Relay 801 operates in this circuit and at its upper front contact places battery potential on the test terminal 804 to mark the trunk as calling to the line finder 800 and at its inner upper front contact closes an obvious circuit for the common start relay 803. Relay 803 operates and closes start circuits for all idle line finders such as 800 having access to the trunk circuit. It will be assumed that line finder 800 is to be used in extending the connection. The operating circuit of this line finder may now be traced from ground, front contact of relay 803, contacts of test jack 805, back contact of test relay 806, upper back contact of relay 50 807, upper back contact of relay 809 to battery through the interrupter contacts and winding of stepping magnet 809.

When the line finder 800 has advanced until the wiper 810 engages the test terminal 804, a circuit is established for test relay 806 extending from battery on test terminal 804, wiper 810, contacts of jack 805 to ground through the upper winding of relay 806. Relay 806 operates opening at its back contact 55 the circuit of magnet 809 and closing at its front contact a circuit from ground at the contact of relay 803, contacts of jack 805, front contact of relay 806, upper winding of relay 811, to battery at the lower normal contacts of relay 808. Relay 811 operates and

extends ground from the front contact of relay 806, over the inner upper front contact of relay 811 to battery through the winding of relay 812 and connects ground over its upper front contact through the lower low resistance winding of relay 806 to the test terminal 804 to mark the calling trunk from seizure by other line finders. With relay 812 operated a circuit is established from ground at its contact, conductor 813, winding 70 of relay 808, wiper 814 to battery through the winding of cut-off relay 802. Relays 802, 808 now operate, relay 802 disconnecting the line relay 801 from the incoming trunk circuit thereby releasing start relay 803, if no other trunk circuit group is calling at the time, to arrest the hunting movements of other line finders that may have been started, and opening the circuit of relay 806.

With relay 808 operated a holding circuit is established for relay 811 before its initial operating circuit is opened by relay 806, extending from ground through the lower winding and lower front contact of relay 811, the lower back contact of relay 815, to battery at the lower alternate contacts of relay 808. At its upper front contacts relay 808 connects the trunk conductors 607, 608 respectively over wipers 816 and 817 to ground through the lower winding of relay 818 and to battery over the upper back contact of relay 819 through the upper winding of relay 818. Relay 818 now operates over the loop previously traced through the contacts of relay 604, and at its front contact establishes a new holding circuit for relay 812. Relay 808 also establishes a circuit for relay 820 extending from battery at its lower alternate contacts through the winding of relay 820, inner upper back contact of relay 819 90 to ground on conductor 813. At its lower front contact relay 808 connects battery over the intermediate upper front contact of relay 811, to the terminals 901 of all link finders which have access to the group of links in which the link of Fig. 8 is located and in a branch circuit to ground through the winding 95 of relay 902.

Relay 902 closes an obvious circuit for relay 903, which at its contacts closes starting 105 circuits for idle link finders such as 900. The circuit for finder 900 may be traced from battery, winding and interrupter contacts of magnet 904, upper back contact of relay 905, contacts of relay 903, contacts of jack 906, 120 back contact of test relay 907 to ground at the normal contacts of jack 908. When the finder 900 finds the calling link circuit, a circuit is established from battery on test terminal 901, test wiper 909, upper winding of relay 907, contacts of jack 906, lower back contact of relay 1001, wiper 911 of steering switch 910 to ground. Relay 907 thereupon 125 operates opening at its back contact the circuit of magnet 904 and closing a circuit from 130

ground at the normal contacts of jack 908, over the front contact of relay 907, winding of relay 912, lower winding of relay 907 to test wiper 909 thereby marking the link circuit busy to other link finders. Relay 912 operates in this circuit establishing an obvious circuit for relay 905.

A circuit is established by relay 905 which may be traced from interrupted ground over the inner lower back contact of relay 913, right winding of tone coil 914, the upper alternate contacts of relay 905 to battery through the winding of magnet 904. Magnet 904 does not, however, operate in this circuit. A dialing tone is now transmitted to the calling subscriber from the left winding of coil 914, which circuit may be traced from the lower terminal of coil 914, upper back contact of relay 915, wiper 946, inner lower back contact of relay 819, inner upper back contact of relay 815, condenser 820, inner upper front contact of relay 808, wiper 817, conductor 608, lower front contact of relay 610 which operated upon the association of the registering device of Fig. 7, condenser 632, wiper 431, front contacts of relays 421 and 407, wiper 419, conductor 208, front contact of relay 210, which operated upon the association of the registering device of Fig. 3, condenser 232, wiper 131, front contacts of relays 123 and 109, wiper 129, thence over the calling line returning over the wiper 128, front contacts of relays 109 and 123, wiper 127, condenser 231, front contact of relay 210, conductor 207, wiper 418, front contacts of relays 407 and 421, wiper 434, condenser 631, front contact of relay 610, conductor 607, wiper 816, upper front contact of relay 808, condenser 821, upper back contact of relay 815, lower back contact of relay 819, wiper 947, inner lower front contact of relay 905, to the upper terminal of coil 914. All of the foregoing functions have been performed responsive to the removal of the calling subscriber's receiver from the switchhook.

Establishment of a call to the center office

When the calling subscriber receives this dialing tone he proceeds to dial the digits of the wanted line number. It will be assumed that the number of the wanted line is 72235 indicative of a line terminating in the center office. In response to dialing the first digit seven, the impulsing relay 204 of the trunk circuit of Fig. 2 releases for each impulse thereby repeating the impulses through the winding of relay 312 in a circuit extending from ground at the lower back contact of relay 204, the intermediate lower front contact of relay 206, wiper 313, the upper intermediate front contact of relay 307, winding of relay 312, inner upper back contact of relay 314, back contact of relay 815 to battery through the winding of stepping magnet 316 of the register 310. Relay 312 operates in

this circuit and being slow to release remains energized during the transmission of the series of impulses and at its back contact opens the previously traced circuit of relay 210 which thereupon deenergizes and shunts the winding of relay 212 from the outgoing trunk dialing loop for permitting the better repetition of impulses over the outgoing trunk circuit. At its upper contacts relay 204 repeats impulses over the outgoing trunk circuit 207, 208 thereby operating impulse repeating relay 604. Relay 604 in turn repeats impulses out over trunk conductors 607, 608 and repeats impulses to the stepping magnet 716 of register 710 of Fig. 7.

When relay 905 operated, a circuit was closed from ground at its inner upper front contact, normal terminal and wiper 924, and interrupter contacts of magnet 925 of steering switch 910 to battery through the winding of relay 923. Relay 923 operates and closes a circuit for magnet 925, over the inner upper front contact of relay 923, to ground at the back contact of relay 918 and at its upper front contact closes a holding circuit for itself. Magnet 925 operates and in doing so opens the circuit of relay 923 which thereupon deenergizes opening the circuit of magnet 925 to advance the steering switch 910 one step.

The impulses of the first digit dialed in addition to setting the registers 310 and 710 of the registering devices at the district and tandem offices, also operate relay 818, which repeats impulses in a circuit from ground at its back contact over wiper 921, the lower front contact of relay 905, winding of relay 918 to battery through the winding of impulsing relay 919. Relay 919 responds to these impulses and repeats the impulses to magnet 1002 of the register 1010, in a circuit extending from battery, winding of magnet 1002, wiper 922, front contact of relay 919 to ground at the back contact of relay 1003. Relay 918 operates in this stepping circuit and being slow to release remains operated until impulses of the digit series cease. Relay 918 closes an obvious circuit for relay 923, which in turn closes a circuit extending from ground at wiper 911, lower front contact of relay 923, windings of relay 926, wiper 927, winding of relay 815 to battery at the lower front contact of relay 808. Relay 815 operates to open the path over which dial tone was transmitted and opens the holding circuit of relay 811 which now releases. Relay 926 at its lower contact establishes a holding circuit for relay 815 and over its own upper winding, lower back contact of relay 913 to ground at the upper back contact of relay 1001 independent of ground at wiper 911.

At the end of the first digit series, relay 918 releases and closes a circuit for magnet 925, over the inner upper front contact of relay 923. Magnet 925 operates opening the cir-

cuit of relay 923 which deenergizes in turn opening the circuit of magnet 925 to advance the steering switch another step. The next four digits dialed by the calling subscriber are in a similar manner registered on the registers 1020, 1030, 1040 and 1050 through the operation of their stepping magnets 1004 to 1007 inclusive, the steering switch 910 advancing one step in the manner previously described above upon the termination of each digit series.

When the second digit has been registered a circuit is established from ground at steering switch wiper 911 to battery thru the winding of relay 1008 which locks to ground over conductor 928 and the upper front contact of relay 905, and closes a circuit for the stepping magnet 1009 of the translator switch 1000. This circuit may be traced from battery, winding and interrupter contacts of magnet 1009, back contact of relay 1011, seventh terminal and wiper 1012 of register 1010, this register having been set into position seven indicative of a call within the exchange system, inner lower front contact of relay 1008 to ground at the upper back contact of relay 1001. The translator now hunts for a terminal 1013 in the lower level of its bank marked by the register 1020. When such terminal is found, a circuit is established for relay 1011, extending from battery, winding of relay 1011, wiper 1014, terminal 1013, wipers 1015 and 1016 of registers 1020 and 1010, normal contacts of relay 1017, to ground at the upper contact of relay 1008. Relay 1011 operates opening the circuit of magnet 1009.

When the third or hundreds digit two has been registered, a circuit is established for relay 1018 extending from ground at wiper 911, to battery through the winding of relay 1018. Relay 1018 operates and locks over its inner lower front contact to ground on conductor 928, and at its lower front contact establishes a circuit for relay 1017 extending from battery through the winding of relay 1017, the lower front contact of relay 1018, front contact of relay 1011, wiper 1012, inner lower front contact of relay 1008, to ground at the upper back contact of relay 1001. Relay 1017 operates and locks over its inner upper front contact to ground on conductor 928 and opens the circuit of relay 1011. The previously traced operating circuit of magnet 1009 is now established to advance the wipers of the translator to hunt for a terminal in its lower bank level marked by the register 1030. When the marked terminal is found, a circuit for relay 1011 is established from battery through the winding of relay 1011, wiper 1014, terminal 1019, wiper 1021 of register 1080, which has been assumed to have been set into position two, lower front contact of relay 1017 to ground at

the upper front contact of relay 1008. The translator has not been set. It is to be noted that if the hundreds digit had been one, the circuit of relay 1011 would have been established directly over the wiper 1021, thereby opening the circuit of magnet 1009 before it became effective to advance the translator wipers off the terminal set including the terminal 1013. Since the thousands digit is two or of even value, a circuit is effective for the wiper switching relay 1024 of the translator extending from battery, winding of relay 1024, wiper 1025 to ground at the upper front contact of relay 1008. This relay thus operates only when the thousands digit is even and is instrumental in selecting one of the pairs of translator wipers 1026, 1027 or 1028, 1029. The particular wiper of the selected pair which is effective is determined by the setting of wiper 1031 of the register 1010 into either position six or seven.

With the translator 1000 set, a circuit is now effective for the stepping magnet 1022 of the translated digit control switch 1060, extending from battery, winding and interrupter contacts of magnet 1022, back contact of relay 1023, upper front contact of relay 1017, front contact of relay 1011, thence as traced to ground at the upper back contact of relay 1001. When the switch 1060 finds the translation point marked by the translator 1000, a circuit is established for relay 1023, extending from battery, winding of relay 1023, wiper 1032, terminal 1033, jumped to terminal 1034 of the translator, thence over wiper 1029, lower front contact of relay 1024, wiper 1031, to ground at the upper front contact of relay 1008. Relay 1023 operates opening the circuit of magnet 1022, to arrest further hunting movement of switch 1060 and closes a circuit for relay 1035 extending from battery, winding of relay 1035, front contact of relay 1023, thence to ground as previously traced. Relays 1036 and 1037 operate in the same manner as relays 1008 and 1018 at the termination of the tens and units digits.

Had the call been outside the exchange area, that is, the 10,000 digit been other than 6 or 7, then the translator 1000 would not have hunted and switch 1060 would have hunted in a circuit extending from battery through the winding of magnet 1022, contact of relay 1023, strapped terminals and wiper 1012 of register 1010 to ground at the back contact of relay 1001, for a terminal in the bank level accessible to its wiper 1032 marked directly by wiper 1031 of register 1010. Returning to a consideration of the operation of the registering devices of the district and tandem offices, upon the termination of the first digit series of impulses, relay 312 releases and closes a circuit for relay 315 extending from battery, winding of

relay 315, off-normal terminal and wiper 309 of register 310, normal terminal and wiper 311 of register 320 to ground at the back contact of relay 312. Relay 315 energizes and locks over its lower contact to ground applied to conductor 353 at the upper front contact of relay 307, and switches the impulsing circuit previously traced from the winding of magnet 316 of register 310 over the upper back contact of relay 322 to the winding of magnet 317 of register 320. Similarly relays 712 and 715 function to prepare the registering device of Fig. 7 to register the second series of impulses upon the register 720.

The second digit two dialed by the calling subscriber now sets the register 320 to its second terminal position. Immediately the second digit register 320 moves off normal, a circuit is prepared to start the rotation of translator switch 330 extending from battery, through the winding and interrupter contacts of magnet 318, the off-normal terminals and wiper 319, lower back contact of relay 321, lower back contact of relay 322, to ground on conductor 353. The terminals in the lowermost bank of register 320 are connected in pairs 1, 2; 3, 4; etc., and are connected by jumpers to terminals 1, 11, 21, etc., in the marking level of the translator switch 330. The translator switch hunts for the marked terminal under the control of test relay 321, but if the first terminal is marked the switch does not move since relay 321 will operate immediately when register 320 leaves normal over a circuit extending from battery, wiper 323, No. 1 terminal and wiper 325 of translator switch 330, upper normal contacts of relay 314 to ground through the winding of relay 321. When the marked terminal, in the case assumed 324, is found, relay 321 operates over the circuit just traced, opening the circuit of stepping magnet 318. When the relay 312 again deenergizes upon the termination of the second series of impulses, with relay 321 operated a circuit is closed for relay 322 extending from battery, winding of relay 322, front contact of relay 321, off-normal terminals and wiper 311 of register 320 to ground at the back contact of relay 312. Relay 322 operates and locks to ground on conductor 353. Similar operations are performed simultaneously in the registering device of Fig. 7.

In response to the dialing of the third digit two, two impulses are repeated by the impulsing relay 204 as before traced through the winding of relay 312, thence over the upper front contact of relay 315, the upper front contact of relay 322 to battery from the winding of stepping magnet 318. It was assumed that the third digit was two and therefore the translator wipers are advanced two steps further. As soon as wiper 325 leaves terminal 326, the circuit of relay 321

is opened. When relay 312 again deenergizes upon the termination of the third digit series of impulses a circuit is established for relay 314 extending from battery through the winding of relay 314, inner lower front contact of relay 322, back contact of relay 321, thence as traced to ground at the back contact of relay 312. Relay 314 upon operating locks over its inner lower front contact to ground on conductor 353. The registering device of Fig. 7 is similarly operated.

The terminals of the four upper levels of translator switch 330 are multiplied in accordance with the size of the various offices of the exchange and are jumpered to the points 336, 337 and 338 in accordance with the distance between the originating office and the other offices. It will be noted that the even numbered terminals of the bank associated with wiper 341 are multiplied to the wiper switching relay 333 and that as the second digit dialed was two, or of even value, relay 333 is operated over wiper 341 and the inner upper front contact of relay 322. In addition the sixth and seventh terminals in the bank of register 310 to which wiper 342 has access are connected to the armatures of relay 333 and in accordance with the energized or deenergized condition of this relay, are connected to either wipers 343 and 344, or 345 and 346 of the translator switch. Since it has been assumed that the register 310 was set into its seventh terminal position and that relay 333 is operated, wiper 344 only is connected in a circuit over wiper 342, the intermediate lower front contact of relay 314 to ground on conductor 353. Since also the translator has been advanced to position its wiper 344 upon terminal 356, this circuit is extended by a jumper to cross-connection point 337.

No record of the denomination of the fourth and fifth digits dialed is taken in the register circuit, but pairs of relays 327, 328 and 329, 331 are energized at the beginning and end of the tens and units digit series respectively under the control of relay 312. Thus, at the beginning of the fourth or tens digit a circuit is established from battery, through the winding of relay 327, back contact of relay 328, lower front contact of relay 314 to ground at the front contact of relay 312. Relay 327 thus operates locking through the winding of relay 328 and over its own contact to ground on conductor 353 but relay 328 being shunted does not operate. When relay 312 deenergizes, however, at the end of the tens digit series, relay 328 operates. At the beginning of the fifth or units digit series relay 312 again operates and establishes, a circuit for relay 329 extending from battery through the winding of this relay, front contact of relay 328, thence as traced to ground at the front contact of relay 312. Relay 329 operates and locks in series

with relay 331 over its own front contact to ground on conductor 353, but relay 331 being shunted at the front contact of relay 312 does not energize in this locking circuit. When, 5 however, relay 312 deenergizes at the end of the units digit series relay 331 operates and establishes a circuit for relay 332 extending from battery through the winding of relay 332, the front contact of relay 331 to ground 10 on conductor 353.

Metering control relays 213 and 214 are now connected over wipers 334 and 335 of the trunk finder 300 and front contacts of relay 332 to cross-connecting points 336 and 15 337 of cross-connecting rack 340. A further point 338 is connected by relay 332 to the winding of relay 339. It has been assumed that for the particular setting of the translator switch in response to the digits 722 20 the translator bank terminal 356 is jumpered to the point 337 and that therefore following the operation of relay 332, a circuit is established for relay 214 extending through the winding of relay 214, wiper 335 over the lower front contact of relay 332, terminal 356, wiper 344, lower front contact of relay 333 which was operated with register 320 in position two, the seventh terminal and wiper 342 of register 310, the intermediate lower 25 front contact of relay 314 to ground on conductor 353. Relay 214 locks to ground on conductor 221. Had the first three digits dialed been, for example, 742, then upon the operation of relay 332 the relay 339 would 30 be operated, and both relays 213 and 214 would have been operated. Had the digits 642 been dialed then relay 339 would not have been operated and relay 213 would have been operated. Thus dependent upon the first 35 40 digits dialed three metering conditions may be established by the operation of both or either of relays 213 and 214.

In addition to selectively operating the meter control relays 214, relay 332 connects 45 direct ground over its upper contact, the inner upper front contact of relay 307, wiper 308 to battery through the winding of relay 211. Relay 211 upon operating establishes a locking circuit for itself, and at its lower 50 back contact opens the holding circuit of relay 307 which now releases in turn releasing all operated apparatus of Fig. 3.

At the registering device of Fig. 7 the registers 710 and 720 have been set in accordance with the first two digits dialed and the translator 730 is set in the same manner as described more in detail in connection with the setting of the registering device of Fig. 3. Since each tandem group is allotted 1000 55 lines, it is known after the first two digits have been received whether the call is local to the tandem group. As the call is not local, a circuit is established following the operation of relay 714 which may be traced from 60 battery through the winding of relay 613,

wiper 734, back contact of relay 727, intermediate lower front contact of relay 714 to ground over conductor 753 and the upper front contact of relay 707. Relay 613 upon operating at its upper front contact connects ground over the normal terminal and wiper 627 of meter impulsing switch 600, conductor 633, wiper 436, the inner upper front contact of relay 421, the upper alternate contacts of relay 412 to the winding of relay 412, thereby shunting relay 412 and causing its deenergization. Relay 412 thereupon removes battery from the test terminal 501 releasing relay 505 and thereby releasing the register sender of Fig. 5. When relay 727 of the tandem office registering device operates at the beginning of the fourth digit 75 the circuit of relay 613 is again opened.

Returning to the operation of the translator sender of the center office it will be recalled 80 that following the setting of the translated digit switch 1060, relay 1035 operated. Upon the operation of relay 1035 a circuit is established from ground at its inner upper front contact, wiper 1041 and terminal 1042 of switch 1060, which it will be recalled was set by the translator into position 1, thence by jumper to battery through the upper winding of skip relay 1043. Relay 1043 is jumpered to the terminal 1042 in view of the fact that 85 only four digits are required to set selectors to complete the desired connection whereas the control switch 1060 is designed to control the sending of five digits. The manner in which the various skip relays and motor control relays, as shown in Fig. 10, may be 90 jumpered, to bank terminals of the control switch 1060, and the manner in which the terminals of impulse counting switch 920 are multiplied to bank terminals of the control 95 switch 1060 and to the banks of the digit registers is disclosed more in detail in Fig. 10 and will be discussed briefly hereinafter. Relay 1043 upon operating establishes an obvious circuit for relay 1044 which locks to 110 ground on conductor 928.

Relay 1035 also establishes a circuit from battery, back contact of relay 1038, or from battery back contact of relay 1039 inner lower front contact of relay 1035, lower front contact of relay 1036, resistance 937, lower back contact of relay 915, normal terminal 916 and wiper 917 of impulse counting relay 920, upper back contact of relay 913, inner lower front contact of relay 905, wiper 947, lower back contact of relay 819, conductor 822, inner upper back contact of relay 1101 to ground through the winding of control relay 1102, which is common to a plurality of 115 selectors 1100. Relay 1102 operates in this circuit and establishes an obvious circuit for relay 1103 which in turn closes a start circuit for switch 1110. This switch functions both as a selector finder and as a marking switch 120 and its operating circuit may be traced from 125 130

battery, winding of magnet 1104, inner lower front contact of relay 1103, normal terminal 1105, wiper 1106, back contact of relay 1107 to ground at the interrupter contacts of magnet 1104. Magnet 1104 operates opening its own circuit and advancing its wipers off normal, the circuit of magnet 1104 is now extended from battery through its winding, off normal segment 1108, wiper 1106, thence to ground 5 at the interrupter contacts of magnet 1104.

- When the switch 1110 has advanced to its terminal position corresponding to the selector 1100 a circuit is established for relay 1107 extending from ground at the upper front 10 contact of relay 1103, winding of relay 1107, lower back contact of relay 1111, wiper 1112, terminal 1109, thence over the circuit traced to battery at the back contact of relay 1038. Relay 1107 operates opening the circuit of 15 magnet 1104 and closing a circuit from ground over the interrupter contacts of magnet 1104, front contact of relay 1107, wiper 1113, terminal 1114, winding of relay 1115 to battery through the winding of relay 1111. Relay 1115 and 1111 operate and lock over 20 the inner upper front contact of relay 1115, upper back contact of relay 1101, conductor 1116, lower normal contact of relay 807 to ground on conductor 813. The operation of relay 1111, releases relay 1107, whereupon 25 the switch 1110 advances until wiper 1106 leaves segment 1108, or into position 11. The first ten contacts of switch 1110 correspond to ten group selectors which may be 30 accessible to switch 1110. Upon reaching position 11 relay 1117 operates in a circuit extending from battery, winding of relay 1117, terminal 1118, wiper 1112, lower front contact of relay 1111, to ground at the upper 35 front contact of relay 1103. A circuit is now established from battery through the winding of relay 1119, lower front contact of relay 1117, intermediate lower front contact of 40 relay 1115, conductor 823, lower back contact of relay 811, inner lower back contact of relay 819, wiper 946, intermediate lower front contact of relay 905, inner lower normal contacts of relay 915 to ground through the winding 45 of relay 929.
- Relays 1119 and 929 operate in series, relay 929 closing a circuit for relay 915, extending from ground at key 930, wiper 931 and normal terminal 932 of counting switch 50 920, front contact of relay 929, winding of relay 915 to battery at the lower back contact of relay 1039. Relay 915 locks over its inner upper front contact, segment 933 to ground on wiper 934, disconnects relay 929 from series connection with relay 1119, and 55 establishes a loop across conductors 822 and 823, over the inner lower front contact of relay 915, terminal 916 and wiper 917 for holding relay 1119 in the group selector operated. Relay 915 also closes a circuit from 60 ground at its upper front contact, interrupter 65

contacts and winding of magnet 935, which operates and advances the counting switch 920 one step off normal from which position it is driven around into normal position under the control of off normal contacts 936. As 70 the wiper 917 passes over the terminals of its level, the circuit of control relay 1119 is intermittently broken.

In response to these impulses relay 1119 transmits stepping impulses from ground at 75 its back contact, over the upper front contact of relay 1117, through the winding of slow to release relay 1120 to battery through the winding of magnet 1104 thus advancing the 80 wipers of switch 1110 to mark a group terminal in the marking level of the group selector 1100. It will be assumed that through the setting of the translated digit control switch 1060 the first two digits dialed by the calling subscriber have been translated into 85 a single digit series of two impulses and therefore when wiper 931 of the digit counting switch 920 reaches terminal 938 a circuit is established from ground at key 930, wiper 931, terminal 938 jumpered to terminal 1045, 90 wiper 1046, back contact of relay 1047 to battery through the winding of relay 939. Relay 939 operates and locks over segment 933 and wiper 934 until the switch 920 passes beyond position 9, and short-circuits the wiper 95 1047 and terminals with which it cooperates to prevent further transmission of impulses to relay 1119 of group selector control switch 1110. When the switch 920 has advanced beyond position nine relay 1119 is held operated over wiper 917 and segment 940 until the switch 920 advances into normal. As the switch 920 passes through position fifteen a circuit is established from ground, wiper 934, terminal 941 to battery through the winding 10 of relay 1047 which operates and locks to conductor 928.

When the control switch 1110 leaves position eleven the circuit of relay 1117 is opened but this relay is held operated by relay 1120 until relay 1119 releases following the return of the digit impulsing switch 920 to normal. Relay 1120 thereupon releases in turn releasing relay 1117 and relay 1117 in turn opens the circuit previously traced over conductor 823 to the wiper 917. A circuit is now closed for advancing the group selector 1100 to hunt for an idle trunk in the group marked by the control switch 1110 which may be traced from battery, winding and interrupter contacts of magnet 1121, inner lower front contact of relay 1115, upper back contact of relay 1122, upper back contact of relay 1117, segment 1123, wiper 1112, lower front contact of relay 1111 to ground at the upper front contact of relay 1103. When switch 1100 has advanced until its test wiper 1125 engages test terminal 1126 of an idle group selector, which may be of the same type as group selector 1100, a circuit is established from ground at the inner 11

lower front contact of relay 1111, lower winding of relay 1122, wiper 1127, terminal 1124, group terminal 1121, wiper 1128, upper front contact of relay 1115, wiper 1125, test terminal 1126 of the idle trunk to battery in the group selector (not shown). Relay 1122 locks over its upper winding, through the winding of relay 1129, front contact of relay 1122, back contact of relay 1117, segment 1123, wiper 1112, front contact of relay 1111 to ground at the front contact of relay 1103. Relay 1129 operates and establishes a circuit for relay 1101 over the intermediate upper front contact of relay 1115, which locks to conductor 1116 and releases relays 1111 and 1115. The group selector control circuit is thus disconnected and relay 1111 releasing closes a circuit from battery, winding of magnet 1104, upper back contact of relay 1111, segment 1130, wiper 1106, back contact of relay 1107 to ground at the interrupter contacts of magnet 1104 whereby the control switch 1110 is returned to normal.

When relay 1101 operated conductors 822 and 823 were extended over wipers 1131 and 1132 to the selected group selector whereupon the circuit previously traced from battery at the back contact of relay 1039 to trunk conductor 822 is completed to ground through a relay in the group selector corresponding to relay 1102. When the control switch associated with this group selector has seized the selector taken for use, the circuit previously traced to ground through the winding of relay 929 is established. The counting switch 920 is now operated in the manner previously described to transmit impulses to the control switch of this group selector until the wiper 931 engages a terminal which has been marked by wiper 1048 of the hundred's register 1030. Since the hundred's register is set into position 2, when the wiper 931 engages terminal 938 a circuit will be established for relay 939 extending from battery, winding of relay 939, lower front contact of relay 1047, upper front contacts of relays 1044 and 1049, which it will be recalled were operated since the particular call does not require the setting of second and third group selectors, upper back contact of relay 1039, wiper 1048, lead 1070 cross-connected to terminal 938, wiper 931 to ground at key 930. Relay 939 stops the transmission of impulses and when the impulsing switch 920 reaches terminal 942 a circuit is established for relay 1039 extending from ground, wiper 934, terminal 942, inner upper front contact of relay 1049 to battery through the winding of relay 1039. Relay 1039 locks to ground on conductor 928. When the switch 920 reaches normal the sender is prepared to transmit the next series of impulses in accordance with the setting of the ten's register 1040.

As previously described in connection with

Fig. 11, the selected group selector functions under the control of its control switch to select an idle final selector such as is shown in Fig. 12. When the final selector is seized the circuit from battery in the sender previously traced over conductor 822 and wiper 831 is extended over the wiper of the selected group selector, conductor 1201, upper back contact of relay 1202, inner upper back contact of relay 1203 to ground through the winding of relay 1301. Relay 1301 operates and closes a circuit for relay 1302 extending from battery, winding of relay 1302, contact of relay 1301, normal terminal 1303 and wiper 1304, normal contacts of relay 1305 to ground at the interrupter contacts of magnet 1306. A circuit is now established for magnet 1307 of the ten's marking switch 1300 extending from battery, through the winding and interrupter contacts of magnet 1307, lower front contact of relay 1302, inner lower back contact of relay 1308 to ground at the back contact of relay 1309. When the marking switch has advanced to a position to select the final selector which has been selected for use, a circuit is established for relay 1309 in a circuit extending from battery on conductor 1201 thence as traced to terminal 1311, wiper 1312, lower back contact of relay 1308, winding of relay 1309, upper back contact of relay 1305 to ground at the interrupter contacts of magnet 1306.

A circuit from battery through the winding of relay 1308, winding of relay 1204, terminal 1313, wiper 1314, inner upper back contact of relay 1315 to ground at the front contact of relay 1309 is now established. Relay 1308 does not operate in this circuit, but relay 1204 operates and locks over its inner upper front contacts to ground placed on conductor 1205 as the preceding group selector, whereupon relay 1308 operates and closes a restoring circuit for marking switch 1300 extending from battery, through the winding and interrupter contacts of magnet 1307, upper back contact of relay 1315, front contacts of relay 1308, wiper 1316 to ground on segment 1317. When the switch 1300 reaches normal, relay 1309 releases and closes a circuit from battery, winding of relay 1315, normal terminal 1318 and wiper 1319, lower front contact of relay 1308 to ground at the back contact of relay 1309. Relay 1315 operates and locks to ground at the upper front contact of relay 1308 and connects battery through the winding of relay 1320, inner lower alternate front contacts of relay 1315, upper back contact of relay 1321, upper front contact of relay 1204, conductor 1206, thence over a wiper of the preceding group selector, wiper 1132, and thence as traced to ground through the winding of relay 929 at the sender. The sender is thus given a signal that the final selector is ready to receive the impulses of the ten's series and the counting

switch 920 then functions in the manner previously described to transmit impulses to the final selector impulsive relay 1320.

In response to each impulse relay 1320 establishes a circuit from ground over its back contact, lower front contact of relay 1315, winding of slow releasing relay 1322, inner upper back contact of relay 1305 to battery through the winding of magnet 1307 of the ten's marking switch 1300. At the end of this digit series relay 1322 releases and closes a circuit from battery through the winding and lower back contacts of relay 1305, back contact of relay 1322, upper front contact of relay 1315, upper alternate contacts of relay 1308, wiper 1316 to ground on segment 1311. Relay 1305 locks over its lower alternate contacts, inner lower front contact of relay 1315 to ground at the upper front contact of relay 1308. At the sender when the wiper 931 of the counting switch encounters the terminal of its bank level marked by wiper 1053 of the ten's register 1040, a circuit is established for relay 939 extending as previously traced to the upper front contact of relay 1049, thence over the upper front contact of relay 1039, the lower back contact of relay 1054, wiper 1053, lead 1055, the register 1040 having been set into position three, terminal and wiper 931 of counting switch 920 to ground at the key 930. Relay 939 stops the impulsive in the manner previously described. When wiper 934 of the counting switch engages terminal 943 a circuit is established therefrom over the inner upper front contact of relay 1039 to battery through the winding of relay 1054 which locks to ground on conductor 928. The sender is now prepared for controlling impulsive in accordance with the setting of unit's register 1050.

Upon the return of the digit counting switch to normal the circuit previously traced for relay 929 through the winding of relay 1320 is again established and relay 929 prepares the loop dialing circuit and starts the counting switch 920 to transmit impulses of the unit's digit series. Relay 1320 responds to these impulses and repeats these impulses from ground over its back contact, over the lower front contact of relay 1315, winding of relay 1322, inner upper front contact of relay 1305, lower back contact of relay 1321 to battery through the winding of magnet 1306 of the unit's marking switch 1310. Upon the release of relay 1322 at the termination of the unit's digit series a circuit is established from battery, winding of relay 1321, wiper 1323, segment 1324, inner lower front contact of relay 1305, back contact of relay 1322, upper front contact of relay 1315, upper alternate contacts of relay 1308 to ground over wiper 1316 and segment 1311. Relay 1321 operates and locks over the inner lower

front contact of relay 1315 to ground at the upper front contact of relay 1308.

When relay 1305 operated upon the completion of the ten's digit series a circuit was completed for advancing the selector 1200 in a group finding movement which may be traced from battery, winding and interrupter contacts of magnet 1207, lower front contact of relay 1204, lower back contact of relay 1325 to ground at the lower front contact of relay 1305. When the selector 1200 has advanced its wiper 1208 to the group terminal 1209 a circuit is established from battery, winding of relay 1325, intermediate lower front contact of relay 1204, wiper 1208, terminal 1209, terminal 1326 and wiper 1319 of ten's marking switch 1300, inner lower front contact of relay 1308 to ground at the back contact of relay 1309. With relays 1325 and 1321 both operated the circuit of magnet 1207 is opened and a circuit is established from battery, intermediate lower front contact of relay 1321, winding of relay 1309, inner upper front contacts of relay 1315, inner upper front contacts of relay 1325 to ground. Relay 1325 now deenergizes again establishing the circuit of magnet 1207 to advance the final selector in a terminal hunting movement under the control of unit's marking switch 1310. When the wiper 1208 engages a terminal marked by the switch 1310 a circuit is established as before traced from the winding of relay 1325 to wiper 1208, thence over a terminal 1210 engaged thereby, terminal 1327, wiper 1328 to ground at the front contact of relay 1309. Relay 1325 operates and stops further hunting of the selector.

If the units digit had been one instead of five relay 1325 would not have released following the setting of the final selector in its group finding movement since it would have been held energized over the circuit previously traced to terminal 1326, wiper 1319, terminal 1329, wiper 1328 to ground at the inner upper front contact of relay 1325. Consequently the final selector switch would not have advanced off of terminal 1209, or the terminal of the first line of the third ten's group.

If the wanted line is free, battery through the cut-off relay of the line over wiper 1211, winding of relay 1212, inner lower front contact of relay 1204, intermediate upper front contact of relay 1321, lower front contact of relay 1325 to ground at the lower front contact of relay 1305 operates relay 1212 which connects relay 1213 to ground on conductor 1205. Relay 1330 also operates in a circuit extending over the upper front contact of relay 1325, inner lower front contact of relay 1321 to ground over the interrupter contacts of magnet 1306 and establishes a circuit from battery, over its contact, lower winding of relay 1202, inner upper front contact of relay 1204 to ground on conductor 1205. Relay 130

1202 now locks over its upper winding, back contact of relay 1214, inner upper alternate contacts of relay 1202 to ground on conductor 1205. Ringing current is now applied to the 5 called line from the ringing current source 1215, winding of relay 1214, upper front contact of relay 1213, upper front contact of relay 1202, lower front contact of relay 1213, wiper 1216, over the called line, returning 10 over wiper 1217, inner lower front contact of relay 1213 to ground at the lower front contact of relay 1202. Ringing tone is transmitted to the calling line over the upper front contact of relay 1213, condenser 1218, lower 15 front contact of relay 1202, thence over the established connection to the calling line. When the called subscriber responds relay 1214 operates releasing relay 1202 to cut off ringing current and to cut through the talking 20 conductors.

At the register sender when the counting switch 920 advanced its wiper 931 during the transmission of the unit's digit series to a terminal of its bank determined by the setting 25 of register 1050, the circuit of relay 931 was established to stop the transmission of impulses. This occurred when wiper 939 engaged its fifth terminal, the circuit of relay 939 extending as previously traced to the 30 lower front contact of relay 1054, thence to wiper 1057, lead 1056, wiper 931 to ground at key 930. As the switch 920 advanced around into normal position and engaged terminal 944 a circuit was established for relay 35 1001 extending from ground, wiper 934, terminal 944, intermediate upper front contact of relay 1054 to battery through the winding of relay 1001. Relay 1001 operates locking to ground at its own upper front contact and 40 at its upper back contact opening the holding circuit of relays 926 and 815 whereupon these relays release, relay 926 opening the circuit of relay 905 which in turn removes holding ground from conductor 928 thereby releasing 45 all operated relays in the sender.

Relay 815 upon releasing connects the 50 trunk conductors 822 and 823 over its back contacts to the windings of supervisory relays 824 and 825 through which talking battery is supplied to the called subscriber. Relay 824 closes an obvious circuit for relay 819 which frees the conductors 822 and 839 from branched connections and opens the circuit of slow releasing relay 820. The circuit for 55 the upper winding of relay 818 which was previously completed over the upper back of relay 819 to the ring talking conductor is now transferred over the front contact of relay 825, front contact of relay 820 so that during 60 the releasing period of relay 820 this winding is disconnected from the tip conductor of the connection extending back through the winding of relay 612 in the trunk circuit of Fig. 6. Since neither of relays 613 and 614 is at the 65 time operated the momentary release of relay

612 completes a circuit for relay 620 extending from battery, winding of relay 620, upper front contact of relay 611, upper back contact of relay 612 to ground at the lower front contact of relay 606. Relay 620 locks 70 to ground on conductor 621 and when relay 612 reenergizes it operates relay 609 over the upper front contact of relay 620 and the front contact of relay 612. Relay 609 now locks 75 and connects battery over the lower back contact of relay 613, upper back contact of relay 614, lower front contacts of relay 609, conductor 633, wiper 436, inner upper front contact of relay 421, upper back contact of relay 412, wiper 448 to ground through the winding of relay 417. Relay 417 operates and locks over the upper front contact of relay 402, opens the circuit of relay 212 at its upper contacts and releases relay 416 which, after an interval determined by its slow releasing characteristic, again closes conductor 208. 80

In response to this momentary opening of conductor 208, relay 212 in the district trunk circuit is momentarily released. Relay 212 85 upon releasing now closes a circuit for relay 220 extending from battery, through the winding of relay 220, upper front contact of relay 211, upper back contact of relay 212 to ground on conductor 221. Relay 220 locks 90 to conductor 221 and as soon as relay 212 again energizes, establishes a circuit for relay 209 extending over the upper front contact of relay 220, the front contact of relay 212 to ground on conductor 221. Relay 209 also 95 locks to conductor 221 and establishes an obvious circuit for the time switch 222 which receives an impulse every two seconds from the master clock circuit. 100

A circuit is also established from battery, 105 through the winding of metering switch magnet 223, wiper 224 and the normal terminal upon which it is resting, contact 225 of the time switch 222 to ground at the intermediate upper front contact of relay 209 for advancing the switch 200 one step off normal, from which position it rotates through a single cycle under the control of interrupter 226. As soon as the time switch 222 leaves normal 110 it opens contact 225 so that when the metering switch 200 reaches normal its advance is arrested. With relay 214 operated as previously described, when the wiper 227 of the metering switch 200 passes over the first, third and fifth terminals of its bank three 115 metering impulses are transmitted over a circuit which extends from metering battery, through resistance 228, the upper front contact of relay 214, terminals and wiper 227 of switch 200, the lower back contact of relay 215, conductor 216, wiper 161, the lower front contact of relay 123, wiper 156 to ground 120 through the message register magnet 155. 125

After three minutes, time switch 222 again closes contact 225 and the metering switch 130

200 again completes a cycle transmitting three additional metering impulses. This sequence of operations continues if the connection is still held for conversation until nearly 5 twelve minutes have elapsed. Ten seconds prior to the completion of the twelve minute period, the timing switch 222 closes contact 229 connecting a source of tone to the calling line as a warning that the twelve minute period is about to elapse. If the calling subscriber does not release the connection at the end of the twelve minute period, the timing switch 222 closes its contact 230 connecting a short-circuiting ground to the winding of 10 relay 117 in the district line circuit over conductor 201, contact 230 to ground at the intermediate upper contact of relay 209. Relay 117 then releases in turn releasing relay 123 whereupon the calling line is disconnected 15 from the windings of relay 204. Relay 204 then releases in turn releasing relays 205 and 206. Following the release of relay 206 the trunk circuit of Fig. 2 is released. Relay 204 also opens the loop circuit extending 20 over conductor 207 and 208 thereby releasing relay 422 which in turn releases relay 414 removing holding ground from conductor 430. All operated relays of the link circuit at the tandem office now release opening the 25 circuit of relay 604 in the tandem trunk circuit.

Relay 604 releases in turn releases all operated relays of the trunk circuit and opens the loop over trunk conductors 607 and 608 30 thereby releasing relay 818 in the center office link circuit followed by the release of relay 812 and all operated relays of the link circuit. Upon the release of relay 812 ground is removed from conductor 1116. Relay 1101 35 in the group selector of Fig. 11 now releases unlocking all operated relays of this selector and at its lower front contact disconnects ground from wiper 1125 thus releasing a relay similar to relay 1101 in the succeeding 40 group selector circuit. This group selector circuit is then restored to normal removing ground from conductor 1205 thereby releasing the operated relays of the final selector.

At the sender, relay 1001 upon operating 45 also establishes an obvious circuit for relay 1058 which in turn establishes a restoring circuit for register 1010 extending from battery, winding of magnet 1002, off-normal terminal and wiper 1059, lower front contact of relay 50 1058 to ground over the interrupter contacts of magnets 1002 to 1007 inclusive. As soon as register 1010 reaches normal wiper 1059 extends the restoring circuit over its normal terminal, wiper 1061 and off-normal terminals of its bank to the winding of magnet 1004. 55 Similarly restoring circuits are established over wipers 1062, 1063 and 1064 for magnets 1005, 1006 and 1007. When register 1059 reaches normal the restoring circuit is extended over wiper 1064 and the normal ter-

70 minal of its bank, the inner upper front contact of relay 1058, the off-normal terminals and wiper 924 of steering switch 910, interrupter contacts of magnet 925 to battery through the winding of relay 923. Relay 923 75 operates and establishes the circuit of magnet 925 which in turn opens the circuit of relay 923. Thus relay 923 and magnet 925 reciprocally control each other to advance the steering switch 910 to normal. When ground is removed from conductor 928 and relay 1008 releases the circuit of relay 1023 is opened and with relay 1058 operated a restoring circuit is closed for translated digit switch 1060 80 extending from battery through the winding and interrupter contacts of magnet 1022, back contact of relay 1023 to ground at the inner lower front contact of relay 1058. When the switch 1060 reaches normal, relay 1023 again 85 operates in a circuit extending over wiper 1032 and the normal terminal of the marking level of switch 1060 to ground at the upper contact of relay 1058. With relay 1023 operated, relay 1035 reoperates in a circuit extending through its winding, the front contact of relay 1023 to ground at the inner lower front contact of relay 1058 and, as soon as the steering switch 910 reaches normal, closes a circuit for shunting down relay 1001. This circuit 90 extends from ground at the normal contact of key 930, wiper 931 and normal terminal 932 of the counting switch 920, back contact of relay 929, upper alternate contacts of relay 1035, wiper 975 and normal terminal of switch 910, inner upper front contact of relay 1001, upper operating winding of relay 1001 to ground at the upper front contact of relay 1001. Relay 1001 thereupon releases, in turn 95 releasing relays 1058, 1023 and 1035. The sender has now been completely restored.

Returning now to the district link circuit 100 relay 123 upon releasing now connects the calling line to the windings of relay 126 which thereupon energizes. If the calling subscriber does not now restore his receiver within thirty seconds, the thermostatic relay 112 operates over the lower front contact of relay 126, the normal terminal and wiper 137 of marking switch 140, the back contact of relay 134, a back contact of relay 118 to off-normal ground on conductor 138. As previously described, relay 112 causes the operation of the calling line fault relay 159 which signals the attendant and causes the release 110 of the district link circuit.

If the calling subscriber terminates the conversation prior to the completion of the twelve minute period, the restoration of his receiver releases relay 204 followed by the release of relays 205 and 206 and the restoration of the remaining equipment employed in the connection. If, however, the calling subscriber holds the connection after the called subscriber hangs up, for a period of thirty 115 seconds, a circuit is established for the ther-

mostatic relay 217 extending over the lower back contact of relay 212, which releases when the called subscriber hangs up, thence to ground at the lower front contact of relay 220. After the expiration of thirty seconds, relay 217 closes its lower contact thereby connecting direct ground to conductor 201 for shunting down relay 117. The forced release of the connection is then caused in the manner previously described. Similarly after the out pulsing loop over trunk conductors 207 and 208 is established by relay 204, if pulsing does not begin the circuit of relay 217 is established over the upper back contact of relay 211 and the inner upper front contact of relay 210 for a sufficient interval to cause relay 217 to start the forced release of the established connection.

In the preceding description it was assumed that meter control relay 214 was operated and that thus for each unit period of conversation three metering impulses were transmitted by switch 200 for operating the calling line message register magnet. Had meter control relays 214 and 213 been operated it is obvious that five metering impulses would have been transmitted and that similarly had relay 213 been operated alone but two metering impulses would have been transmitted.

Call to or through the main office

If the digits registered in the register sender of Figs. 9 and 10 indicate a call to be completed at the main office, or through the main office to another center office, then in response to the transmission of the first translated digit under the control of switch 1060 the group selector of Fig. 11 would be set in the manner previously described to select a trunk circuit extending to the main office and terminating therein in a selector switch 1400 such as is disclosed in Fig. 14. When connection is made with this selector and relay 1101 operates, the conductor 822 is extended over wiper 1131 to ground through the winding of relay 1401 and relay 1401 operates from battery supplied at the sender completing an obvious circuit for relay 1402. Relay 1402 in turn operates and establishes a circuit from battery, winding of relay 1403, front contact of relay 1402, wiper 1404 and normal terminal of marking switch 1410 to ground at the lower normal contact of relay 1403. Relay 1403 operates and locks over the front contact of relay 1402 to ground at its lower front contact and connects battery from the upper back contact of relay 1405, inner upper front contact of relay 1403, winding of coil 1406, thence to wiper 1132 and over the circuit previously traced to ground through the winding of relay 929. Relay 929 thereupon operates to close the dialing loop at the sender and to start the impulse counting switch 920 to transmit the next series of im-

pulses under the control of switch 1060. For this type of call it will be assumed that the switch 1060 has been set into such a position as to render the wiper 1065 of switch 1060 effective to control the number of impulses in this digit series.

At the selector of Fig. 14 relay 1401 responds to these impulses and repeats the impulses from ground at its back contact, over a front contact of relay 1403, thence in parallel through the winding of slow releasing relay 1407 and over the lower back contact of relay 1408 to battery through the winding of magnet 1409 of the marking switch 1410. Relay 1407 upon operating establishes a circuit for relay 1411 extending over the inner upper back contact of relay 1405, front contact of relay 1407, lower back contact of relay 1405 to ground at the inner lower front contact of relay 1403. Relay 1411 locks over its inner upper front contact, the upper back contact of relay 1408 to ground at the inner lower front contact of relay 1403. When the last impulse is received, relay 1407 deenergizes and with relay 1411 operated, establishes a circuit from battery, winding and inner lower back contact of relay 1405, lower front contact of relay 1411, back contact of relay 1407, lower back contact of relay 1405 to ground over the locking circuit of relay 1411. Relay 1405 operates and locks over its inner lower alternate front contact to ground at the inner lower front contact of relay 1403 and closes the circuit of magnet 1412 of the selector 1400 extending from battery, winding and interrupter contacts of magnet 1412, back contact of relay 1413, inner lower alternate front contact of relay 1405 to ground at the inner lower front contact of relay 1403. When a free trunk is found in the group marked by wiper 1414 of the marking switch 1410 a circuit is established for relay 1413 extending from battery, over the test terminal 1415 of the trunk circuit, test wiper 1416, front contact of relay 1403, test wiper 1417, group terminal 1418, wiper 1414, lower high resistance of relay 1413, lower front contact of relay 1405 to ground at the inner lower front contact of relay 1403.

Relay 1413 thereupon operates and locks over its low resistance winding, winding of relay 1419, upper front contact of relay 1413 to ground at the inner lower front contact of relay 1403 and opens the circuit of magnet 1412 to arrest further movement of the selector. Relay 1419 upon operating closes an obvious circuit for relay 1408 which holds relay 1411 operated in a circuit through the winding of relay 1411, inner upper front contact of relay 1405, back contact of relay 1407, inner upper front contact of relay 1408 to ground at the front contact of relay 1401. A circuit is now established from battery, lower contact of relay 1401, winding of coil 1420, upper front contacts of relays 1408 and

1411 to ground in the group selector selected by the selector 1400. When such group selector is ready to receive impulses a pulsing relay therein is connected over wipers 1422, 5 the inner lower front contacts of relays 1411 and 1408 to ground through the winding of relay 1423. Relay 1423 thereupon operates and connects battery through coil 1406, wiper 1132, thence as traced to ground through the 10 winding of relay 929 in the sender. Relay 929 thereupon closes an impulsing loop extending through the winding of relay 1401 and relay 1401 then functions under the control of the digit counting switch 920 15 to repeat a subsequent series of impulses for setting the next selector switch, for example, a group selector of the type shown in Fig. 11. In response to the first impulse of this digit series relay 1401 releases 20 and closes a circuit from ground at its back contact for relay 1407 thereby causing the release of relay 1411. When relay 1401 re-energizes a circuit is now closed from ground at its front contact, inner upper front contact of relay 1408, front contact of relay 1407, winding of relay 1424 to battery at the upper contacts of relay 1405. Relay 1424 thereupon 25 repeats the impulses to the next group selector over its front contacts and the upper normal contacts of relay 1411. When the last 30 impulse of this series is transmitted relay 1407 releases again operating relay 1411. In the same manner impulses are repeated to operate subsequent group selectors and a 35 final selector of the type shown in Figs. 12 and 13.

When the last digit series has been transmitted relay 1001 in the sender functions as before described to release the sender and to 40 cut through the talking circuit from the calling line to the called line. When the called subscriber answers relay 1423 operates and connects battery through coil 1406 to the circuit extending back to relay 825 in the center office link whereby a signal is retransmitted 45 toward the calling office to indicate the response of the called subscriber in the manner previously described.

50 *Call initiated by a subscriber local to the center office*

In the diagram of Fig. 16 a subscriber's line S4 terminating in the center office is 55 shown as having access to a link circuit in the center office over a first and second line finder. To simplify the disclosure it will be assumed that access may be had over a single line finder as is disclosed more in detail in Fig. 15. When such a subscriber, for example, 60 subscriber 1590 initiates a call, relays 1501, 1591 and 1503 operate and the line finder 1500 is started through the operation of magnet 1509 to hunt for the calling line. When such calling line is found relay 1506 65 operates in a circuit extending from bat-

tery, front contact of relay 1501, terminal 1504, wiper 1510, contacts of jack 1505 to ground through the lower winding of relay 1506. Relay 1506 operates opening at its back contact the circuit of magnet 1509 and closing at its front contact a circuit from ground at the contact of relay 1503, contacts of jack 1505, front contact of relay 1506, lower winding of relay 1511 to battery at the lower normal contacts of relay 1508. Relay 1511 operates and extends ground from the front contact of relay 1506 over the upper intermediate front contact of relay 1511 to battery through the winding of relay 1512 70 and connects ground over its lower front contact and the upper low resistance winding of relay 1506 to the test terminal 1504 to mark the calling line from seizure by other line finders. With relay 1512 operated a circuit is established from ground at its contact, conductor 1513, upper back contact of relay 1507, lower back contact of relay 1519 to battery through the winding of relay 1508. Relay 1511 now locks 75 over its upper winding and inner upper front contact, lower back contact of relay 1521 to battery at the lower front contact of relay 1508. Relay 1508 also connects the winding of relay 1515 over its inner lower front contact, wiper 1514 to battery through the winding of cut-off relay 1502, connects the windings of relay 1518 to the calling line loop thereby operating relay 1518, and connects battery over its lower front contact, the inner lower front contact of relay 1511 to the terminal 945 of the link finder 900 and in parallel therewith to battery through the winding of start relay 902. Relay 902 operates as 80 previously described to start the finder 900 hunting for the calling link. When the link is found relays 907, 912, 905, 923 and magnet 925 function as previously described to prepare the sender of Figs. 9 and 10 for the reception of impulses dialed by the calling subscriber.

It will be assumed that the calling subscriber dials the number of another subscriber whose line terminates in the same office and that the number is 72235. In response to dialing the first digit, relay 1518 repeats impulses from ground, over its back contact, lower front contact of relay 905, winding of relay 918 to battery through the winding of relay 919. Relay 919 responds to the impulses and causes the setting of the register 1010 in the manner previously described. Relay 918 operates relay 923 which in turn establishes a circuit extending from battery at the lower front contact of relay 1508, lower winding of relay 1521, terminal 948, wiper 927, windings of relay 926, inner lower front contact of relay 923 to ground on wiper 911. Relay 1521 in operating disconnects dial tone and releases relay 1511. From this point the sender functions to register the remaining 100 105 110 115 120 125 130

digits dialed and to set the translator 1000 and translated digit switch 1060 in the manner previously described.

When the digits have all been registered relay 1035 operates establishing a circuit from battery, inner, lower back contact of relay 1039, inner lower front contact of relay 1035, lower front contact of relay 1036, back contact of relay 915, terminal 916, wiper 917, upper back contact of relay 913, inner lower front contact of relay 905, wiper 947, terminal 949, back contact of relay 1522, upper back contact of relay 1511, inner upper back contact of relay 1523 to ground through the winding of relay 1102. Relay 1102 operates in turn operating relay 1103 and starting the switch 1110 to hunt for the selector 1510. When switch 1110 finds selector 1510 a circuit is established for relay 1107 over the lower back contact of relay 1111, wiper 1112, terminal 1133, thence as traced to battery at the back contact of relay 1039 in the sender. Relay 1107 then operates opening the circuit of magnet 1104 and closing a circuit from ground over the interrupter contacts of magnet 1104, front contact of relay 1107, wiper 1113, terminal 1134, winding of relay 1524 to battery through the winding of relay 1111. Relays 1524 and 1111 operate and lock over the inner upper front contact of relay 1524, upper back contact of relay 1523 to ground on conductor 1513. Relay 1111 releases relay 1107 whereupon the switch 1110 is advanced to position 11 operating relay 1117, all as previously described. A circuit is now established from battery, winding of relay 1119, lower front contact of relay 1117, intermediate lower front contact of relay 1524, upper back contact of relay 1519, terminal 950, wiper 946, intermediate lower front contact of relay 905, lower normal contact of relay 915 to ground through the winding of relay 929. Relays 929 and 1119 operate and perform the functions previously described to cause the setting of marking switch 1110 under the control of translated digit switch 1060.

When the series of impulses transmitted to the switch 1110 cease, relay 1120 deenergizes releasing relay 1117 thereby closing the operating circuit of magnet 1525 of selector 1510 which extends from battery, through the winding and interrupter contacts of magnet 1525, inner lower front contact of relay 1524, back contact of relay 1122, back contact of relay 1117, segment 1123, wiper 1112, lower front contact of relay 1111 to ground at the upper front contact of relay 1103. When the switch 1510 has advanced until its test wiper 1528 engages terminal 1529 of an idle group selector, a circuit is established from ground at the inner lower front contact of relay 1111, lower winding of relay 1122, wiper 1127, terminal 1124, group terminal 1527, wiper 1526, upper front contact of relay 1524, wiper 1528,

test terminal 1529 of the trunk to battery at the group selector. Relay 1122 locks and operates relay 1129 which in turn establishes a circuit extending from battery through the winding of relay 1523, intermediate upper front contact of relay 1524 to ground at the front contact of relay 1129. Relay 1523 now locks over its upper front contact to ground on conductor 1513 and releases relay 1524. The group selector control circuit is now disconnected and the switch 1110 is restored to normal as previously described. From this point the sender proceeds to set the selected group selector and a final selector in the manner described to extend the connection to the wanted line, the connection being now extended over wipers 1530 and 1531 of group selector 1510.

When the sender has completed the transmission of all impulses relay 1001 operates releasing relays 926, 1521 and 905 as previously described whereupon the register sender is restored to normal. Relay 1521 upon releasing connects the wipers 1530 and 1531 to the retard coil 1532 and winding of supervisory relay 1533 and upon the response of the called subscriber relay 1533 operates. As the call is of a local character neither zone relay 1534 or relay 1535 is operated and a circuit is established for relay 1519 extending from battery, lower winding of relay 1519, lower back contacts of relays 1534 and 1535, front contact of relay 1533 to ground on conductor 1513. Relay 1519 now locks over its inner lower front contact and upper back contact of relay 1507 to ground on conductor 1513. A circuit is also established in parallel with relay 1519 to battery through the upper normal contacts and winding of relay 1522 which also operates and locks to ground on conductor 1513. Relay 1508 is now held operated in a circuit from battery through its winding, front contacts of relay 1519, lower front contact of relay 1515 to ground at the front contact of relay 1518.

When the calling subscriber releases at the end of the conversation relays 1518, 1515 and 1512 release and a single metering impulse is transmitted from battery, over the inner upper back contacts of relays 1534 and 1535, lower front contact of relay 1519, inner lower back contact of relay 1507, back contact of relay 1515, wiper 1536 to ground through the message register magnet 1537. The remaining apparatus employed in the connection is restored in the manner previously described.

For calls originated by the subscriber 1590 to be terminated outside of the central office, provision is made for zone metering in accordance with three zones by cross-connecting points 951, 952 and 953, to terminals in the translator digit switch 1060 corresponding to the offices of such zones. Thus, when relay 1035 operates at the beginning of out pulsing, ground will be connected over the

inner upper front contact of relay 1035, wiper 1066, thence to one of the three cross-connection points. If ground is connected to point 951 a circuit is established over wiper 954, terminal 955, to battery through the winding of zone relay 1534 which locks to ground on conductor 1513. Similarly, if ground is connected to point 952 a circuit is established over wiper 956, terminal 957 to battery through the winding of zone relay 1535 which locks to conductor 1513. If ground is connected to point 953, relay 958 operates in turn operating and locking both relays 1534 and 1535. With either or both relays 1534 and 1535 operated, when the called subscriber answers and relay 1533 operates, relay 1519 is not operated but relay 1522 operates.

It will be assumed that relay 1535 is operated and that upon the operation of relay 1522 the timing switch 1540 is operated over front contacts of relays 1535 and 1522 from the clock circuit. This timing switch may be of the type disclosed more in detail in Fig. 2. When the timing switch closes its contact 1538 a circuit is closed from ground, over the lower front contact of relay 1535, the lower front contact of relay 1522, normal terminal and wiper 1539 and magnet winding 1541 of impulsing switch 1520. Switch 1520 advances from normal and under the control of interrupter 1542 completes a revolution closing, as it passes over its terminals 1, 3 and 5, a circuit from battery, wiper 1543, upper front contact of relay 1535, front contact of relay 1515, wiper 1536 to ground through message register magnet 1537. Thus the register 1537 is operated three times. If the conversation continues the timing switch 1540 upon again closing its contact 1538 after an interval of three minutes, operates the switch 1520 through another revolution to again operate the message register. The timing switch functions thereafter in the manner described herein in connection with Fig. 2. It will be obvious that had relay 1534 been operated instead of relay 1535 but two message register operating impulses would have been transmitted for each period of conversation and similarly if both relays 1534 and 1535 had been operated, five impulses would have been transmitted.

In Fig. 18 the manner in which banks of the sender registers 1010 to 1050 inclusive and the three upper levels of translated digit switch 1060 are cross-connected to the counting switch 920, and the manner in which terminals of the four upper levels of the translator switch 1000 could be connected to the lower level of switch 1060 have been shown more in detail. The terminals of the group 1800 may be connected as required to the three upper levels of the switch 1060 whereby the counting switch 920 may count three digit series in succession under the control of wipers 1046, 1068 and 1065 of switch 1060. As shown in

this figure if the first digit registered upon register 1010 is 1, 2 or 3 indicating a call outside of the exchange area, the translated digit switch 1060 is set directly over wiper 1012 and cross-connections to the first three terminals in the lower marking level of switch 1060.

It is necessary in certain circumstances to send a less number of series of impulses and for this purpose levels of switch 1060 to which wipers 1041 and 1066 have access are jumped to operate relays shown at the right of the figure. When relay 1035 of Fig. 10 operates, following the completion of dialing, ground is connected to wipers 1041 and 1066 of switch 1060 thence to terminals upon which these wipers have been positioned thereby operating certain of these relays which may be jumpered to such terminals. In the foregoing description it was assumed that the terminal upon which wiper 1041 was set was connected to the winding of relay 1043 and that therefore two sets of impulses which would otherwise be controlled by switch 1060 over wipers 1068 and 1065 were omitted.

If, for example, relay 1069 is operated over its upper winding, relay 1044 of Fig. 10 is operated and digits are sent only under the control of wipers 1046 and 1065 of switch 1060. If relay 1069 is operated over its lower winding, relays 1044 and 1047 are operated and a single digit is sent under the control of wiper 1065. Similarly if relay 1070 is operated, relays 1044, 1049 and 1039 are operated and the second, third and fourth digits are omitted, a single digit being transmitted under the control of wiper 1046 and two digits being transmitted under the control of the tens and hundreds registers.

If relay 1051 is controlled over its upper winding the third digit is controlled over wiper 1067 of the thousands register rather than over wiper 1065 of switch 1060. If relay 1051 is controlled over its lower winding, then it also functions to operate relay 1038 to prevent the transmission of any digit impulses until the unit digit has been dialed by the calling subscriber. Relay 1052 if cross-connected, functions similarly to relay 1051 but also operates relay 1001 after the third series of digit impulses has been transmitted to stop impulsing and to release the sender. The cross-connection of terminals 951, 952 and 953 to terminals of switch 1060 to which wiper 1066 has access for controlling zone metering has already been described.

Call initiated at tandem office for a local subscriber

When a call is initiated on a line local to the tandem office, assuming that such calling line is similar to the calling line 101 of Fig. 1 and appears in the bank of line finder 400 of Fig. 4, the line relay of such line closes the circuit of common start relay 403 and all line

finders having access to that line are started. It is assumed that the finder 400 is the finder which is to be used, its operating circuit is controlled in the manner previously described and when it seizes the calling line the link finder 500 is started to associate the register sender of Fig. 5 and the group selector 410 is operated to seize an outgoing trunk in the manner previously described. When a trunk, for example, the trunk shown in Fig. 6, is seized an idle registering device such as that shown in Fig. 7 is associated therewith in the manner previously described. As soon as the apparatus associated with the distant end of trunk 607-608 is ready to receive impulses the calling subscriber receives a dial tone as previously described whereupon he commences to dial the digits of the wanted line number.

Since the calling subscriber wishes a connection with a subscriber's line which terminates in the tandem office, it will be assumed that he dials the number 63256 and that in response to the first two digits, registers 710 and 720 are positioned respectively in positions six and three and that following the setting of the register 720 the translator switch 730 is started to hunt for the group of terminals marked by the wiper 723 of the register 720. Since the register wiper 723 is in engagement with its third terminal the translator under control of its wiper 725 will advance until the wiper 725 engages terminal 726 when the further movement of the translator will be arrested by the operation of relay 721. Following the termination of the second digit series relay 722 operates and locks to ground on conductor 753. These operations are all performed in the manner set forth in detail in connection with the description of Fig. 3.

With relay 722 operated and the translator wiper 745 in engagement with terminal 754, which terminal is commoned to the succeeding nine terminals of the same level corresponding to the tandem group of 1000 lines, a circuit is established for relay 732 extending from battery, through the winding of relay 732, cross-connection point 749, terminal 754, wiper 745, upper back contact of relay 733, wiper 742 of register 710 in position six, lower front contact of relay 722 to ground on conductor 753. Relay 732 upon operating establishes a circuit for relay 615 extending over wiper 647, the intermediate upper front contact of relay 732, back contact of relay 731 to ground on conductor 753. Relay 615 locks over its upper front contact to ground on conductor 621 and at its upper back contact removes busy potential from terminal 601 thereby releasing relays 425 and 428 in the tandem link circuit. With relay 425 released a circuit is established for relay 426 extending from battery, through the winding and lower normal contacts of relay 426, inner upper front contact of relay 429, back contact

of relay 425 to ground at the inner upper front contact of relay 407. Relay 429 operates and locks over its inner lower front contact to ground on conductor 430 through the winding of relay 437. The energization of relay 615 also opens the circuit of relay 421 which upon releasing reconnects the windings of relay 422 to the conductors of the calling line over front contacts of relay 407 and line finder wipers 418 and 419. Following the release of relay 421 ground for holding relay 414 operated is supplied from the front contact of relay 422.

The group selector 410 in addition to having access to outgoing trunk circuits also has access to groups of trunks terminating in third group finders. The terminals of the bank level to which wiper 427 has access, which correspond to third group finders, are commoned and connected to a contact on relay 438. Since relay 438 operated in a circuit extending through its winding, wiper 515, upper back contact of relay 514 to ground on conductor 553, upon the seizure of the link circuit by the link finder 500, these commoned terminals are connected over the inner upper front contact of relay 438; upper front contact of relay 426, through the lower winding of test relay 425 to ground at the inner upper front contact of relay 412. The group selector 410 is now started to hunt for an idle third group finder by a circuit extending from battery, through the winding and interrupter contacts of magnet 423, intermediate upper back contacts of relay 424, back contacts of relay 425 to ground at the front contact of relay 407. When an idle third group finder is found relay 425 operates in the circuit previously traced to the strapped terminals of group selector 410, thence over wiper 427, inner upper front contacts of relay 426, wiper 435 to battery potential on test terminal 439 of the trunk terminating in an idle third group finder. Relay 425 upon operating locks as before described over its upper winding in series with relay 428.

Relay 428 upon operating establishes a circuit for relay 424 extending from battery, through the winding of relay 424, lower front contact of relay 437, which operated in the locking circuit of relay 426, to ground at the front contact of relay 428. The tandem link circuit is now in condition to receive the last three digits of the wanted line number which have been assumed to be 256. In response to the dialing of the first of these digits relay 422 functions as a repeating relay and upon each deenergization repeats an impulse over a circuit which may be traced from ground at its back contact, upper front contact of relay 437, wiper 516, lower front contact of relay 507, winding of slow to release relay 517 to battery through the winding of pulsing relay 518. Relay 518 in turn repeats impulses over a circuit extending from its low-

er front contact, lower back contact of relay 514 to battery through the winding of stepping magnet 519 of the hundreds register 510. At the end of the first series of impulses relay 517 deenergizes and establishes a circuit for transfer relay 514 extending from battery, through the winding and inner lower normal contacts of relay 514, off-normal terminals and wiper 521 of register 510 to ground at the back contact of relay 517. Relay 514 operates and locks to ground on conductor 553 and transfers the impulsing circuit from the winding of stepping magnet 519 to the winding of stepping magnet 522 of tens register 520 over the lower back contact of transfer relay 523. In response to the next digit series relay 518 now repeats impulses to the magnet 522 and at the end of this digit series relay 523 operates in a circuit extending from battery, through its winding and upper normal contacts, off-normal terminals and wiper 524 of register 520 to ground at the back contact of relay 517. Relay 523 then locks to ground on conductor 553 and transfers the pulsing circuit from magnet 522 to magnet 525 of the units register 530. In response to the last digit series relay 518 repeats impulses to the stepping magnet 525. The registers 510, 520 and 530 have now been set to register the digits 256.

As soon as the register 510 has registered the first of these digits a circuit is closed which may be traced from battery, over the upper front contact of relay 514, inner upper front contact of relay 526, inner upper back contact of relay 527, upper back contact of relay 528, intermediate lower front contact of relay 507, wiper 509, inner upper front contact of relay 524, lower back contact of relay 440, to wiper 434, thence to ground through a control relay in the third group finder, not shown. When the group finder is ready to receive impulses from the sender of Fig. 5, a circuit is established by the control relay of the group finder extending from battery thereto to the wiper 431, thence over the upper back contact of relay 440, the lower front contact of relay 434, wiper 531, inner lower front contact of relay 507, inner upper normal contacts of relay 528, lower normal contacts of relay 527 to ground through the winding of relay 532. Relay 532 thereupon operates and closes a circuit for relay 527 extending from battery, winding of relay 527, contact of relay 532 to ground over the normal terminal 533 and wiper 534 of impulse counting switch 540. Relay 527 thereupon locks over its lower front contact to ground over the segment 535 and wiper 536 of counting switch 540 and releases relay 532. At its inner front contacts relay 527 also extends the circuits previously traced from wipers 434 and 431 in a closed loop over wiper 542 of switch 540. At its upper front contact relay 527 also establishes an obvious

operating circuit for stepping magnet 538 of switch 540 whereby the switch operates step-by-step interrupting the impulsing loop extending to the third group finder at the wiper 542 at each step.

When the wiper 534 reaches the terminal 539 marked by wiper 541 of register 510, which it has been assumed has been positioned in position two, a circuit is established from ground, over wiper 534, terminal 539, wiper 541, upper back contact of relay 526 to battery through the winding of relay 537. Relay 537 operates closing a permanent loop of the out pulsing circuit in shunt of the wiper 542 thus stopping the transmission to the group finder of effective stepping impulses. Relay 537 also locks over its lower contact to ground over segment 535 and wiper 536. When the switch 540 advances beyond segment 543 the loop is closed over wiper 542 and segment 544. When wiper 536 advances beyond segment 535 the holding circuits of relays 527 and 537 are opened and these relays release, but switch 540 continues to advance into its normal position by means of a circuit closed over its off-normal switch contacts 545. When the wiper 534 passes over the terminal 546 an obvious circuit is closed for relay 526 which locks over its inner lower front contact to ground on conductor 553. The operation of the third group finder has thus selected a group of final selector switches and an idle one of such switches is selected in the well-known manner.

Upon the selection of the final selector a circuit is extended from battery at the upper contact of relay 514, over the inner upper front contact of relay 526, wiper 547 and the off-normal terminals of its bank if at this time the units digit has been registered, thence as traced to wiper 534 to ground in the final selector. When the final selector is ready to receive impulses of the tens digit it connects battery over the circuit established therefrom to the wiper 431, thence as traced to ground through the winding of relay 532. Relay 532 again operates in this circuit and in turn operates relay 527 to close the out pulsing loop over wiper 542 and starts the impulsing switch 540 in a second revolution. When wiper 534 leaves the terminal 533, relay 532 deenergizes, but relay 527 is held operated over wiper 536 and segment 535. As soon as wiper 534 reaches the terminal of the lower level of switch 540 upon which marking potential has been placed by wiper 548 of the tens register 520, which it was assumed has been set into position five, a circuit is effective from ground on wiper 534, over wiper 548, back contact of relay 549, the upper front contact of relay 526 to battery through relay 537. Relay 537 operates and performs the functions previously described. Switch 540 advances to its normal position and in passing terminal 550 establishes a circuit for re-

lay 549 extending from ground, wiper 536, terminal 550, lower front contact of relay 526 to battery through the winding of relay 549. Relay 549 operates and locks over its upper contact to ground on conductor 553.

With switch 540 in its normal position relay 532 is again operated from the final selector and the counting switch then makes another revolution for transmitting impulses of the units series to the final selector. With relay 549 operated when the wiper 534 reaches a terminal marked by the wiper 551 of the units register 530 a circuit is established from ground on wiper 534, over wiper 551, the lower front contact of relay 549, the upper front contact of relay 526, for relay 537. In the manner previously described relay 537 stops the transmission of further impulses and when the wiper 536 reaches terminal 552 a circuit is established over the inner upper front contact of relay 549 to battery through the windings of relay 508. Relay 508 operates and locks over its windings and intermediate upper front contact, at its upper front contact short-circuits relay 513 and at its lower back contact opens the holding circuit of relay 505. Relay 505 in turn releases relays 512 and 507 and relay 512 in turn removes locking ground from conductor 553 for releasing all relays locked thereto. Upon the short-circuiting of relay 513 current flowing from ground on conductor 553, through the winding of relay 413 is increased to such an extent that relay 413 operates, locks and extends the talking conductors over its upper and inner lower contacts over wipers 434 and 431, wipers of the third group finder and wipers of the final selector to the called line. Upon the response of the called subscriber, talking current is supplied to the called line through the windings of coil 432 and the winding of supervisory relay 433.

Relay 508 also establishes a restoring circuit for register 510 extending from battery, through the winding of magnet 519, wiper 554 and the off-normal terminals of its bank, the inner upper front contact of relay 508 in series over the interrupter contacts of magnets 519, 522 and 525 to ground at the contacts of jack 555. When the register 510 reaches normal the restoring circuit is extended from wiper 554 and its normal terminal to wiper 556 and off-normal terminals of register 520 to battery through the winding of magnet 522. When register 520 reaches normal this circuit is further extended over wiper 556 and its normal terminal, wiper 557 to the winding of magnet 525. As soon as the register 530 reaches normal this circuit is further extended over wiper 557 and its normal terminal to the inner lower front contact of relay 508 thereby shunting relay 508 and causing its release. All operated appa-

ratus of the sender of Fig. 5 has now been restored to normal.

Should the sender fail to complete its functions within a predetermined period after the completion of the transmission of the hundreds impulses, i. e., after relay 526 operates and establishes the circuit of thermostatic relay 509, relay 509 closes its upper contact operating relay 528 which locks to ground on conductor 553, shunts one winding of relay 513 from the circuit of relay 413 to permit the operation of the latter relay and connects the tone coil 561 to the calling line over its upper front contacts and the front contacts of relay 413. Relay 509 also opens the circuit of relay 505 thereby releasing the sender. The subscriber receiving the tone is apprised of the fact that the connection cannot be established and proceeds to release the connection.

On a call within the tandem office repeated metering on a single tariff is provided, but a variable tariff may be provided, if desired. The destination of the call is indicated by the hundreds digit registered by register 510, and if the call is such as requires repeated metering, ground is connected over wiper 558, cross-connection point 559 which will be assumed to be jumpered to the second position terminal of the bank with which wiper 558 is associated, thence over wiper 560 to battery through relay 441. Relay 441 thus operates and locks to ground on conductor 430 before the sender is released as above described.

When the called subscriber answers and relay 433 operates a circuit is established from ground on conductor 430, front contact of relay 433 to battery through the winding of relay 440. Relay 440 operates and locks to ground on conductor 430 and at its inner upper front contact connects the clock circuit to the timing switch magnet 442. This timing switch is similar to the timing switch shown more in detail in Fig. 2. As soon as the timing switch 442 closes contact 443 with relay 441 operated a circuit is closed for the magnet 444 of the metering impulsing switch 420 extending from ground over contact 443, normal terminal, wiper 445 and magnet 444 of the impulsing switch, inner upper front contact of relay 441 to battery at the lower front contact of relay 440. As soon as the switch 420 leaves normal, ground is supplied for advancing it through a complete revolution to normal from interrupter 446 in which position it is arrested until the timing switch again closes contact 443 after an interval of three minutes. As the wiper 447 passes over the first and third terminals of its bank a circuit is established from battery, over wiper 447, upper alternate contacts of relay 441, wiper 448 of the line finder 400, thence to ground through the calling line message register magnet, thus operating

the message register twice. As the timing switch 442 continues to advance the switch 420 will rotate through a cycle for each three-minute period of conversation. Just prior to the expiration of twelve minutes the calling subscriber will receive a warning tone and if he does not disconnect immediately a peremptory disconnection will take effect at the end of the twelve minute period in the manner previously described in connection with Fig. 2. When the calling subscriber restores his receiver relay 422 releases in turn releasing relay 414 whereupon the remaining relays of the tandem link circuit release.

If repeated metering is not required the jumper to the cross-connection point 559 in the sender is omitted and relay 441 is therefore not operated. When therefore relay 440 operates following the response of the called subscriber, metering current is applied but once from battery, over the lower front contact of relay 440, the upper back contact of relay 441, wiper 448 and thence to the message register of the calling line. In this case the circuit of impulsing switch 420 is not effective since it is open at the upper front contact of relay 441.

Call initiated at district office for a local subscriber

When a call is initiated on line 101, for example, for a line terminating in the bank of selector 110, the circuits function in the manner described to extend the connection to the center office and to associate the registering devices of Figs. 3, 5, 7, 9 and 10 with the established connection. It will be assumed that for this connection the calling subscriber has dialed the digits 74125 and that in response thereto the wiper 344 of the translator 330 of Fig. 3 has been positioned on terminal 357. When therefore relay 314 operates following the termination of the third digit series, since the terminal 357 is jumpered to cross-connection point 349, relay 332 operates and establishes a circuit for relay 215 extending over wiper 347, the intermediate upper front contact of relay 332, back contact of relay 331 to ground on conductor 353. At its upper front contact relay 332 closes a circuit extending from ground, over the inner upper front contact of relay 307, wiper 308 to battery through the windings of relays 210 and 211, thereby causing the operation of these relays. It having been assumed that connection is to be made with the line of a local subscriber which may be reached over the wipers of group selector 110, no cross-connection is made between terminal 357 and the cross-connection points 336, 337 and 338 and therefore relays 213, 214 and 339 are not operated at this time and no discriminating signal is therefore sent to the district link circuit over conductor 216 upon the operation of relay 215.

At its upper back contact relay 215 disconnects battery potential from conductor 201 thereby releasing relay 117 in the link circuit whereupon relay 117 releases in turn releasing relay 123. The release of relay 123 in turn opens the circuit of relay 204 in the trunk circuit releasing relays 205 and 206 of the trunk circuit and relays 305 and 307 of the register circuit. The release of relay 307 removes holding ground from conductor 353 thereby releasing operated relays 314, 315, 322 and 332 and in turn releasing relays 333 and 215. A circuit is now established for restoring the register 320 extending from battery, through the winding and interrupter contacts of magnet 317, off-normal terminals and wiper 348 of register 320, back contact of relay 307 to ground at the off-normal contacts 354 of translator switch 330. When the register 320 reaches normal the operating circuit for magnet 316 of register 310 is established from battery, through the winding and interrupter contacts of magnet 316, wiper 349 and the off-normal terminals of the bank with which it cooperates, the normal terminals and wiper 348 of register 320, thence to ground as traced to off-normal contacts 354. When the register 310 reaches normal the operating circuit of magnet 318 of translator switch 330 is established from battery through the winding and interrupter contacts of magnet 318, the normal terminal and wiper 349 of register 310, thence as traced to ground. Its restoring circuit is opened when the translator reaches normal and opens contacts 354. Trunk finder 300 has no normal position and remains in contact with the terminals of the trunk circuit last used. All apparatus of the trunk circuit of Fig. 2 and register of Fig. 3 is now in normal condition.

Upon the release of relay 204 the circuit previously traced through the windings of relay 604 is opened, whereupon this relay releases, in turn releasing relays 605 and 606 of the trunk circuit of Fig. 6 and relay 705 and 707 of the registering device of Fig. 7. The release of relay 707 initiates the release of all operated apparatus of this registering device in the same manner as previously described in connection with Fig. 3. Relay 606 upon releasing also opens the circuit previously traced for relay 421 and this relay releases, removing holding ground from the winding of relay 414. Also relay 422 is again connected to the incoming trunk conductors 207 and 208 by the release of relay 421 which does not operate at this time since these trunk conductors have been opened at the district link circuit. Therefore there being no holding circuit effective for relay 414, it releases, removing holding ground from conductor 430 and thereby releasing all operated relays of the tandem link circuit. Line finder 400 and group selector 410 being of the non-homing

type remain in their operated positions. The release of relay 604 also releases all operated apparatus at the centre office.

At the district link circuit of Fig. 2 upon the release of relay 123 the windings of relay 126 are connected to the calling line loop over the contacts of relay 109 before slow to release relay 124 has had time to release following the release of relay 123, and a new holding circuit for relay 124 is therefore established over the upper front contact of relay 126 to ground over conductor 138 and the upper front contact of relay 109. When the calling subscriber now dials the tens digit which was assumed to be two, relay 126 releases for each impulse and establishes a circuit for the tens marking switch magnet 132 which extends from battery, through the winding of magnet 132, lower back contact of relay 133, winding of relay 134, back contact of relay 113 which released upon the operation of relay 126, back contact of relay 126 to ground on conductor 138. Slow to release relay 134 operates in series with magnet 132 and remains operated until the tens series of impulses terminates.

As soon as the marking switch 140 leaves normal the group selector 110 starts hunting by reason of a circuit for its stepping magnet extending from battery, through the winding of magnet 114, lower back contact of relays 115 and 116, off-normal terminals and wiper 135 of marking switch 140 to ground at the back contact of relay 117. When the impulses of the tens digit have been completely transmitted relay 134 releases and a circuit is established in parallel from battery, through the upper winding of relay 136 and the winding of relay 133, over the lower normal contacts of relay 118, wiper 137 and off-normal terminals of switch 140, back contact of relay 134, inner upper back contact of relay 118 to off-normal ground on conductor 138. Relay 133 locks itself over its inner lower front contact to ground at the back contact of relay 142 and changes the impulsive circuit controlled by relay 126 from the winding of magnet 132 to the winding of magnet 139 of units marking switch 150 which is now set in response to the dialing of the units digit five. Relay 136 locks over its locking contact and lower winding and back contact of relay 145 to off-normal ground on conductor 138.

When the group selector 110 reaches the terminal 170 of its marking level marked by the setting of the tens marking switch the marking switch having been positioned in position 2, a circuit is established for relay 117 which may be traced from battery, off-normal terminals and wiper 141 of marking switch 140, winding of relay 117, wiper 121, terminal 170, wiper 119 to ground at the upper back contact of relay 118. Relay 117 now opens the circuit of the stepping magnet 114 of the group selector and closes the circuit of re-

lay 118 extending from battery, through the upper winding of relay 118, the upper intermediate front contact of relay 133 to ground at the front contact of relay 117. Relay 118 then locks over its lower winding and inner lower front contact to off-normal ground on conductor 138 and switches marking ground at its upper contacts from wiper 119 of marking switch 140 to the wiper 143 of the units of marking switch 150. Until the marking switch 150 moves beyond its first terminal position relay 117 is held operated from ground over wiper 143, wiper 119, terminal 170, wiper 121, thence as traced through the winding of relay 117 to battery at wiper 141 so that if the units digit is one the group selector does not move further.

It has been assumed, however, that the units digit dialed was five and therefore when marking switch 150 moves beyond position 1, relay 117 releases and closes the circuit of magnet 114 of the group selector to advance it one step whereupon relay 117 again operates. In this manner the group selector follows the setting of the units marking switch step by step. When the units series of impulses ceases, relay 134 again deenergizes and establishes a circuit for relay 142 extending from battery, through the winding of relay 142, off-normal terminals and wiper 144 of the units marking switch 150, lower front contact of relay 118, off-normal terminals and wiper 137 of tens marking switch 140, back contact of relay 134, inner upper front contact of relay 118 to ground at the front contact of relay 117. Relay 142 opens the locking circuit of relay 133 and during the releasing time of slow to release relay 133 a circuit is established for the test relay 146 extending from ground at the upper front contact of relay 142, the inner upper front contact of relay 133, upper winding of relay 142 to the test wiper 122, thence over the test terminal of the wanted line 160 to battery through the cut-off relay 148. If the line is idle, relays 148 and 146 operate and relay 146 locks over its lower winding and intermediate lower contact to off-normal ground on conductor 138. At its upper front contacts relay 146 switches through the talking connection from wipers 127 and 131 through condensers 149 and 151, back contacts of relay 123 and front contacts of relay 109 to wipers 128 and 129. At its inner lower front contact the test wiper 122 is connected to test wiper 125 so that the cut-off relays 103 and 148 of the calling and called lines are connected in parallel through the winding of relay 109 to ground at the front contact of relay 124.

Ringing current is now applied to the called line from the ringing current source 152 through the winding of ringing cut-off relay 145, the upper front contact of relay 136, the inner upper front contact of relay 130

146, wiper 131, thence over the called line 160 and through the substation bell returning over wiper 127, the upper front contact of relay 146, the inner upper front contact of relay 136 to ground at the lower front contact of relay 142. A ringing tone is transmitted to the calling line over the upper back contact of relay 133, condensers 153 and 151, thence as traced over the calling line. When 10 the called subscriber answers, relay 145 energizes releasing relay 136 to disconnect the source of ringing current and ringing tone and to connect the windings of the back bridge relay 154 to the conductors of the 15 called line. Relay 154 now operates in a circuit extending from battery, through its lower winding, upper back contact of relay 136, inner upper front contact of relay 146, wiper 131, thence over the called line, returning over 20 wiper 127, the upper front contact of relay 146, to ground through the upper winding of relay 154.

A circuit is now effective for operating the calling line message register 155 which may 25 be traced from ground, through the winding of message register magnet 155, wiper 156, lower front contact of relay 146 to battery through the inner lower back contact of relay 136. Upon the termination of the conversation, when the calling subscriber restores his 30 receiver, relay 126 releases followed by the release in turn of relays 124 and 109. When relay 109 releases it removes holding ground from conductor 138 thereby releasing all 35 other operated relays of the link circuit and releasing the cut-off relays 103 and 148 of the calling and called lines. With relay 124 deenergized, a restoring circuit is established for marking switch 140 extending from battery, through the winding and interrupter 40 contacts of magnet 132, off-normal terminals and wiper 157, to ground at the back contact of relay 124. When switch 140 reaches normal the winding of magnet 132 is disconnected from wiper 157 and ground from wiper 157 is extended over wiper 158 and the off-normal terminals of its bank through the interrupter contacts and magnet winding 139 45 of marking switch 150. Switch 150 is thereby restored to normal in which position the circuit of magnet 139 is opened. Group selector 50 110 returns to normal upon the seizure of the link circuit for the next call.

If the calling subscriber holds the line for 55 thirty seconds after the called subscriber restores his receiver and releases back bridge relay 154, a circuit became established for the thermostatic relay 112 extending from battery, through the winding of relay 112, 60 the lower front contact of relay 126, the upper back contact of relay 154, the inner upper back contact of relay 136 to ground at the lower front contact of relay 142 which is effective to connect battery over the upper 65 contacts of jack 107, wiper 111, the back

contact of line relay 102 to ground through the upper winding of fault relay 159. Relay 159 upon operating locks over its lower winding in a circuit extending over the calling line to ground at the upper contact of relay 159, and at its inner upper front contact connects a shunt over wiper 125 thereby causing relay 109 to deenergize and release the connection. The calling line cut-off relay 103 is also operated by relay 159, thereby preventing 75 the line relay 102 from reoperating and an alarm circuit is closed over the lower contact of relay 159 to apprise the attendant that the calling subscriber has not restored his receiver as he should. As soon as the calling subscriber 80 hangs up, relay 159 releases and restores the calling line to its normal condition.

In the foregoing description it was assumed that the wanted local line was reached over the wipers of the group selector 110. Had 85 the called subscriber dialed 73125 for reaching a local line terminating in group selector 120 or 64125 for reaching a local line terminating in group selector 130, the connection would be established in the manner fully described in our copending application, Serial No. 434,215, filed concurrently herewith. Since the manner in which such other local 90 connections are established is not material to the present invention, no description thereof 95 will be given herein.

In Fig. 17 an alternative arrangement for interconnection between a sender and a selector has been illustrated. In accordance with this modification when the sender is ready to 100 transmit a series of impulses to a selector switch, a circuit is established from battery at the back contact of relay 1038, out over one trunk conductor to the selector switch through the winding of relay 1701, the winding of high resistance relay 1700, thence back to the sender to ground through the winding of relay 929. Due to the resistance of relay 1700 only relay 1701 operates in this 105 circuit and prepares the selector for receiving impulses. When the selector is ready to receive impulses a shunt is closed around the winding of relay 1700 whereupon relay 929 in the sender operates and relay 1701 is controlled in the manner previously described 110 to cause the setting of the selector switch. At the end of impulsing the short circuit is again removed from relay 1700 and the sender 115 functions to prepare for initiating the impulsion of the next selecting stage.

What is claimed is:

1. In a telephone exchange system, a plurality of offices, subscribers' lines terminating in each of said offices, switching apparatus operative in response to the initiation of a call on a line in the first of said offices to extend a connection in tandem through all 125 of said offices, a digit registering device in each of said offices, and means in each office responsive to the control of a subscriber in 130

said first office for simultaneously causing the registration of digits of called line numbers upon the registers of a registering device of each of said offices.

5 2. In a telephone exchange system, a plurality of offices, subscribers' lines terminating in each of said offices, switching apparatus operative in response to the initiation of a call on a line in the first of said offices to 10 extend a connection in tandem through all of said offices, a plurality of digit registering devices in each of said offices, means responsive to the initiation of a call in said first office to associate an idle registering device 15 with the established connection at each of said offices, and means in each office responsive to the control of a subscriber in said first office for simultaneously causing the registration of digits of called line numbers upon 20 the registers of the associated registering devices of each of said offices.

3. In a telephone exchange system, a first office, a second office, subscribers' lines terminating in said first office, switching apparatus in said first office operative in response to the initiation of a call on a subscriber's line to extend a connection from said first office to said second office, a digit registering device in each of said offices, and 25 means in each of said offices responsive to subscriber control for simultaneously causing the registration of digits of a called line numbers upon the registers of the registering devices of each of said offices.

35 4. In a telephone exchange system, a first office, a second office, subscribers' lines terminating in said first office, switching apparatus in said first office operative in response to the initiation of a call on a subscriber's line to extend a connection from said first office to said second office, a plurality of digit registering devices in each of said offices, means responsive to the initiation of a call to 40 associate an idle registering device with the established connection at each of said offices, and means in each office responsive to subscriber control for simultaneously causing the registration of digits of called line numbers upon the registers of the associated 45 registering devices at each of said offices.

5. In a telephone exchange system, a first office, a second office, subscribers' lines terminating in said first office, trunk lines extending between said offices, switching apparatus in said first office operative in response to the initiation of a call on a subscriber's line to extend a connection over an idle one of said trunk lines to said second 55 office, a digit registering device common to said trunk lines at said first office, a digit registering device in said second office, and means in each of said offices responsive to subscriber control for simultaneously causing the registration of digits of called line 60

numbers upon the registers of the registering devices of each of said offices.

6. In a telephone exchange system, a district office, a tandem office, a center office, a main office, subscribers' lines terminating in each of said offices, switching apparatus at said first two offices operative in response to the initiation of a call on a line in said district office to extend a connection in tandem therethrough to said center office, a digit registering device in each of said first three offices, and means under the control of a subscriber in said first office for simultaneously causing the registration of digits of called line numbers upon the registers of a registering device in each of said first three offices.

7. In a telephone exchange system, a district office, a tandem office, a center office, a main office, subscribers' lines terminating in each of said offices, trunk lines extending between said district office and said tandem office, trunk lines extending between said tandem office and said center office, trunk lines extending between said center office and said main office, switching apparatus at said first two offices operative in response to the initiation of a call on a line in said district office to extend a connection in tandem over idle ones of said trunk lines to said center office, a digit registering device at said district and tandem offices common to the trunk lines outgoing therefrom respectively, a registering device at said center office, and means under the control of a subscriber in said first office for simultaneously causing the registration of digits of called line numbers upon the registers of said registering devices.

8. In a telephone exchange system, a plurality of offices, subscribers' lines terminating in each of said offices, trunk lines outgoing from each of said offices, switching apparatus in each of said offices operative in response to the initiation of a call in the first of said offices to extend a connection in tandem from said first office to the last of said plurality of offices over idle trunk lines, a digit registering device in each of said offices, means under subscriber control for simultaneously causing the registration of digits of called line numbers upon the registers of the registering devices at each of said offices, and means controlled by the registering device of each of said offices if the digits registered upon the registering devices thereof indicates that the call is to be terminated in such office for releasing all operated apparatus beyond that particular office.

9. In a telephone exchange system, a first office, a second office, subscribers' lines terminating in said first office, trunk lines extending between said offices, switching apparatus in said first office operative in response to the initiation of a call on a subscriber's line to extend a connection over an idle one of said 130

trunk lines to said second office, a digit registering device in each of said offices, means in each office responsive to subscriber control for simultaneously causing the registration of digits of called line numbers upon the registers of the registering devices at each of said offices, and means controlled by the registering device of said first office if the digits registered indicate that the call is to be terminated at the first office for releasing all operated apparatus beyond said first office.

10. In a telephone exchange system, a first office, a second office, a third office, subscribers' lines terminating in each of said offices, trunk lines extending between said first and second offices, trunk lines extending between said second and third offices, switching apparatus in said first and second offices operative in response to the initiation of a call in said first office to extend a connection in tandem from said first office to said third office over idle trunk lines, a digit registering device in each of said offices, means under subscriber control for simultaneously causing the registration of digits of called line numbers upon the registers of the registering devices at each of said offices, means controlled by the registering device of said first office if the digits registered indicate that the call is to be terminated at said first office for releasing all operated apparatus beyond said first office, and means controlled by the registering device of said second office if the digits registered indicate that the call is to be terminated at said second office for releasing all operated apparatus beyond said second office.

11. In a telephone exchange system, an office, subscribers' lines terminating therein, trunk lines outgoing from said office, switching apparatus in said office operated in response to the initiation of a call to extend a connection over an idle trunk line, a digit registering device in said office for registering certain digits of called line numbers, means under subscriber control for causing the registration of said certain digits upon the registers of the registering device of said office, a second registering device at said office, normally ineffective for registering the remaining digits of called line numbers, and means controlled by the first registering device if the digits registered thereon indicate that the call is to be terminated locally for releasing the trunk outgoing from said office and for rendering said second registering device effective.

12. In a telephone exchange system, an office, subscribers' lines terminating therein, link circuits each terminating in selector switches, trunk lines outgoing from the banks of said switches, means operative in response to the initiation of a call to associate a calling line over an idle one of said link circuits with an idle trunk, a plurality of first registering

devices common to said trunk circuits, a plurality of second registering devices common to said link circuits, means operative upon the seizure of a link circuit and a trunk circuit for associating a first registering device with such trunk circuit and a second registering device with said link circuit, said second registering device being normally ineffective to register dialed impulses, means under subscriber control for causing the first digits of a called line number dialed to be registered upon the registers of said first registering device, and means controlled by said first registering device if the digits registered indicate that the call is to be terminated locally for releasing said trunk and said first registering device and for rendering said second registering device effective to register the remaining digits of the called line number.

13. In a telephone exchange system, an office, subscribers' lines terminating therein, trunk lines outgoing from said office, switching apparatus in said office operative in response to the initiation of a call to extend a connection over an idle trunk line, a first digit registering device in said office for registering certain digits of called line numbers, a second digit registering device in said office for registering the remaining digits of called line numbers, said second digit registering device being normally ineffective, means under subscriber control for causing the operation of said registering devices, and means controlled by the first registering device if the digits registered therein indicate that the call is to be terminated over an out-going trunk line for releasing said second registering device without operating it.

14. In a telephone exchange system, a first office, a second office, subscribers' lines terminating in each of said offices, switching apparatus in each of said offices, switching apparatus in each of said offices operative in response to the initiation of a call in the first office to extend a connection in tandem through said offices, a digit registering device in the first office for registering certain digits of called line numbers, a registering device in said second office for registering all of the digits of called line numbers, means under subscriber control for simultaneously causing the registration of certain of said digits upon the registers of the registering device at each office, means controlled by the registering device of said first office if the digits registered therein indicate that the connection is to be terminated locally for releasing the operated apparatus beyond said first office, and means controlled by the registering device of said second office for controlling the termination of the call if the registration of said first digits indicates that the call is outgoing from said first office.

15. In a telephone exchange system, an office, subscribers' lines terminating therein,

switching apparatus operative in response to the initiation of a call to extend an outgoing connection from said office, a digit registering device in said office having registers for registering certain digits of called line numbers and means for recording when the remaining digits of said line numbers have been completely dialed, and means under the control of said recording means for releasing said registering device when all of the digits of a called line number have been dialed.

16. In a telephone exchange system, an office, subscribers' lines terminating therein, switching apparatus operative in response to the initiation of a call to extend an outgoing connection from said office, a digit registering device in said office having registers for registering certain digits of called line numbers and relays for recording when the remaining digits of called line numbers have been completely dialed, and means under the control of said recording relays for releasing said registering device when all of the digits of a called line number have been completely dialed.

17. In a telephone exchange system, a plurality of offices, subscribers' lines terminating in each of said offices, switching apparatus operative in response to the initiation of a call on a line in the first office to extend a connection in tandem through all of said offices, a plurality of digit registering devices in each of said offices, means responsive to the initiation of a call in said first office to associate an idle registering device with the established connection at each of said offices, means for transmitting a dialing tone to the calling line when a registering device has become associated at each office, and means in each office responsive to dialing control of a subscriber in the first office for simultaneously causing the registration of digits of called line numbers upon the registering of the associated registering devices at each of said offices.

18. In a telephone exchange system, a register sender for controlling selector switches to establish connections between subscribers' lines comprising registers for registering the digits of wanted line numbers, a single-motion step-by-step translator switch having a plurality of wipers and corresponding levels of bank terminals, wiper switching means, and means controlled in response to the setting of certain of said registers for operating said wiper switching means and for setting the selected wiper upon a particular bank terminal.

19. In a telephone exchange system, a register sender for controlling selector switches to establish connections between subscribers' lines comprising registers for registering the digits of wanted line numbers, a single-motion step-by-step translator switch having a plurality of wipers and corresponding levels

of bank terminals, means controlled over one of said wipers and the corresponding level of terminals in accordance with the setting of certain of said registers for setting said wipers upon particular terminals of their respective levels, and wiper selecting means controlled in accordance with the setting of certain other of said registers for selecting a particular one of the other wipers and the bank terminal upon which it is standing.

20. In a multi-office telephone exchange system, a register sender for controlling selector switches to establish connections between subscribers' lines comprising registers for registering the digits of wanted line numbers, a single-motion step-by-step translator switch having a plurality of wipers and corresponding levels of bank terminals, wiper switching means, means controlled in response to the setting of certain of said registers for operating said wiper switching means, and for setting the selected wiper upon a particular bank terminal, a control switch having a wiper and bank level corresponding to each office designation impulse series to be transmitted from the sender and as many terminal positions as there are offices, and means controlled from selected bank terminals of said translator for setting said control switch.

21. In a multi-office telephone exchange system, a register sender for controlling selector switches to establish connections between subscribers' lines comprising registers for registering the digits of wanted line numbers, a single motion step-by-step translator switch having a plurality of wipers and corresponding levels of bank terminals, wiper switching means, means controlled in response to the setting of certain of said registers for operating said wiper switching means and for setting the selected wiper upon a particular bank terminal, a control switch having a wiper and bank level corresponding to each office designation impulse series to be transmitted from the sender and as many terminal positions as there are offices, a marking wiper and marking bank level for said control switch, and means controlled over said marking level and the selected bank terminal of said translator for setting said control switch.

22. In a multi-office telephone exchange system, a register sender for controlling selector switches to establish connections between subscribers' lines comprising registers for registering the digits of wanted line numbers, a translator switch, means for setting said translator switch in accordance with the joint setting of certain of said registers, a control switch having a wiper and bank level corresponding to each office designation impulse series to be transmitted from said sender and as many terminal positions as there are offices, means controlled from the set position of said

translator switch for setting said control switch, and means operated over certain levels of said control switch for varying the number of impulse series to be transmitted.

23. In a telephone exchange telephone system, a register sender for controlling selector switches to establish connections between subscribers' lines comprising registers for registering the digits of wanted line numbers, a single-motion step-by-step translator switch having a plurality of wipers and corresponding levels of bank terminals, a wiper selecting means for selecting either one of two pairs of said wipers in accordance with the setting of the first of said registers, means controlled by the second of said registers in accordance with whether said second register has been set into an odd or even position for selecting one or the other of the selected pair of wipers and means controlled jointly by the second and third of said registers for positioning the selected wiper.

24. In a multi-office telephone exchange system, a register sender for controlling selector switches to establish connections between subscribers' lines comprising registers for registering the digits of wanted line numbers, a translator switch, means for setting said translator switch in accordance with the joint setting of certain of said registers, a control switch having a wiper and bank level corresponding to each office designation impulse series to be transmitted from said sender and as many terminal positions as there are offices, means controlled from the set positions of said translator switch for setting said control switch, an impulse counting switch the terminals of which are multiplied to the bank terminals in the several levels of said control switch, and means for successively rendering the wipers of said control switch effective whereby said counting switch successively controls the transmission of a plurality of impulse series for routing a call to the office in which a wanted line terminates.

25. In a multi-office telephone exchange system, a register sender for controlling selector switches to establish connections between subscribers' lines comprising registers for registering the digits of wanted line numbers, a translator switch, means for setting said translator switch in accordance with the joint setting of certain of said registers, a control switch having a wiper and bank level corresponding to each office designation impulse series to be transmitted from said sender and as many terminal positions as there are offices, means controlled from the set position of said translator switch for setting said control switch, relays operated over certain levels of said control switch for varying the number of impulse series to be transmitted, an impulse counting switch the terminals of one level of which are multiplied to the bank terminals in the several levels of

said counting switch for determining the number of impulses in each series to be transmitted, and relays controlled sequentially over another bank level of said counting switch by successive operations of said counting switch and cooperating with said first relays for rendering wipers of said control switch successively effective to control the transmission of a plurality of series of impulses.

26. In a telephone exchange system, a register sender for controlling selector switches to establish connections between subscribers' lines comprising registers for registering the digits of wanted line numbers, an impulse counting switch successively controlled in accordance with the setting of said registers for transmitting a plurality of series of impulses, a trunk outgoing from said sender and terminating in a selector switch, a test relay in said sender, a control relay in said switch, means in said sender for establishing a circuit for said control relay over one conductor of said trunk when said sender is ready to transmit a series of impulses to said switch, means in said switch controlled by said relay for operating said test relay over another conductor of said trunk when said switch is ready to receive impulses, and means controlled by said test relay to establish a closed impulsing loop at said sender and to initiate the transmission of a series of impulses to said switch.

In witness whereof, we hereunto subscribe our names this 19th day of February, 1930.

WILLIAM HATTON.
CHARLES DE VRIENDT.
ERNEST JEAN ROUSSEAU.
